COMMUNICATION AND POSTING SYSTEM

Joseph C. Marshall, Baldwin, and Merton L. Haselton, Rye, N. Y., assignors to The Teletregister Corporation, New York, N. Y., a corporation of Delaware

Application April 17, 1940, Serial No. 330,058

30 Claims. (Cl. 177—353)

This invention relates to a communication and posting system, for example, for scheduling, dispatching and the control of airway traffic, and more particularly to a system for transmitting, recording, and posting airport and airway flight control information on announcement or bulletin boards in which the information thus posted may be received from a local transmitter, such as a telegraph keyboard transmitter, or from transmitters remotely situated with respect to the posting and recording apparatus, the last named transmitters being located at ground stations or within aircraft in flight.

In systems now in general use for recording and posting flight plans and flight progress reports of aircraft and other messages relative to the control of aircraft in flight, hereinafter referred to as airway traffic control systems, it is the general practice to post this information upon bulletin or announcement boards manually by the use of chalk or crayon, one or more attendants being required at the bulletin or announcement boards for this purpose. As is well known, manual methods of posting such a board possess the disadvantage of errors introduced by the posting attendant, non-uniformity of the characters posted and, furthermore, the obscurement of the board by the attendant in posting the same.

More specifically, such systems employ manual posting boards comprising removable slats or cardholders individual to each of the flights posted and to the various marker or fix classifications and which are interchanged in accordance with the expected or estimated time of passage or arrival of aircraft at the various reporting or marker points en route and at the airport. The time sequence of flight data posting may be changed from time to time during the progress of the flights as the result of conditions affecting the progress of aircraft such as poor visibility, ice, sleet, changes in the direction and velocity of the wind, the necessity for blind landings and other emergency conditions. The flight progress boards upon which this information is posted comprise section associated with the check points along the various aircraft routes, and the general practice employed is to post the flight control information with chalk or crayon at the traffic control centers on cards mounted on removable slats or cardholders as previously stated and remove the cardholders from the display board successively in accordance with the markers or fix points traversed by the aircraft in flight. The cards thus removed are placed in the files as a record of the flights.

5 The information posted on the cards usually comprises the flight designation symbols followed by a section number, if any, information as to whether the flight is bound toward or away from the control station, the airway traffic control's estimated time when the aircraft will pass over or land at each marker point of the flight route, 10 the pilot's estimated time of traversing each marker point, the time the aircraft actually passes over or lands at each marker point, the expected approach time when the pilot may receive instructions to start his approach to a landing field, proposed altitude at which a clearance has been issued to cross each marker, the altitude 15 at which the aircraft actually crosses the various markers and the landing sequence number assigned to landings under instrument conditions.

20 In addition to the foregoing, certain other information is usually posted on the flight progress boards such, for example, as an indication that a clearance through a marker or fix has been issued, an indication of a flight over the airport, an indication of a stop en route and, in expected approach time, indication that an aircraft has 25 been cleared to the airport control tower or range station, that there will be no delay in landing, or that, if a delay is encountered, the degree of such delay is unknown.

30 Local communication facilities comprising well known telephone or telegraph equipment are employed to establish communication between the airline companies' dispatch and radio offices, airport control tower or towers, the local communications operator of the airway traffic control, a government regulating bureau, local military operations officers, if any, and nearby airports. All conversations over these telephones are usually recorded on records by Ediphone or Dictaphone machines and the records thus obtained are preserved for a period of several days or weeks before eradicating the same. In addition to the disadvantages inherent in manual posting systems, errors in the record may result from improper pronunciation of the information to be recorded, 45 additional errors may result from the interpretation of the information received over the telephone, and the rate at which the flight information may be posted manually on the various flight progress announcing boards is necessarily slow.

50 One of the objects of the present invention is the provision of an automatic posting and recording system in which the foregoing disadvantages are obviated and which is adapted to perform satisfactorily all the functions of the systems heretofore proposed or now in general use, and

in which the circuits employed are relatively simple, with a minimum number of circuits and connections, without substantial duplication of posting and transmitting devices, and which is adapted to employ to a large extent conventional low price telephone and telegraph equipment, and in which the cost of installation and maintenance is comparatively low, and the possibility of failure of the apparatus and circuits is reduced to a minimum.

Another object of the invention is to provide a system of the character disclosed in which a relatively simple transmitting structure is employed to control the operation of a flight progress board over a single channel of communication and to cause the information posted on the board to be recorded automatically by a recording device.

Another object of the invention is the provision of circuit arrangements and parts therefor whereby the information received is selectively posted on a flight progress display or bulletin board under control of signals over an incoming line or communication channel without the intervention of an attendant.

Another object of the invention is the provision of means for controlling the operation of a flight progress board from an airplane or other aircraft in flight.

An additional object of the invention resides in a novel and improved arrangement whereby the posted information is received from a local keyset or from one of a plurality of other channels of communication, as the case may be, in accordance with the time relationship of the signals received over the channels of communication with respect to the operated condition of the keyset.

Another object resides in the provision of a novel and improved arrangement of circuits and parts whereby the order of appearance, time or sequence of the information posted on the flight display board may be varied at will in accordance with the signals received from the keyset.

Another object is the provision of means for automatically selecting for operation a group of posting devices associated with a desired flight identification number and classified with respect to a plurality of markers or fixes regardless of the position of the group of posting devices on the display board.

Another of the objects of the present invention resides in the provision of means for receiving signals comprising information relative to the control of airway traffic over a channel of communication and automatically classifying and posting the same in accordance with the results of such classification.

An additional object is the provision of means whereby a single keyset operation causes the flight information posted by a selected group of posting devices to be transferred to any other group of posting devices and the information posted by the intermediate groups of posting devices to be shifted automatically to certain others of the posting devices in either direction in accordance with the numerical relation between the selected and other groups of devices.

Still other objects, advantages and improvements will be apparent from the following description taken into consideration with the accompanying drawings in which.

Fig. 1 is a view, in diagrammatic form, of certain transmitting and receiving apparatus includ-

ing a seeker mechanism suitable for use with the invention.

Fig. 2 shows a keyset in diagrammatic form adapted for use with the system.

Fig. 3 is a view, represented diagrammatically, of a section of the announcing or bulletin board.

Fig. 4 shows a receiving distributor controlled by signals received from the transmitting apparatus of Fig. 1.

Fig. 5 shows a group of storage and decoding relays controlled by the distributor of Fig. 4 and certain storage devices for automatically selecting a desired group of posting devices in accordance with the signals received by the receiving apparatus of Fig. 1.

Fig. 6 shows groups of storage devices and associated control relays for changing the sequence of the information posted on the devices of Fig. 3.

Fig. 7 shows a transmitting distributor for actuating the devices of Figs. 3 and 5 and certain sequence mechanism comprising a rotary switch and a plurality of control relays.

Fig. 8 shows a code suitable for use with the system.

Fig. 9 illustrates one arrangement of the bulletin or announcement board on which the flight control information is posted.

Fig. 10 is a diagram showing the arrangement of the various sheets comprising the system and.

Fig. 11 is a diagram showing the complete system.

In general, in a system of the character comprising the present invention, diagrammatically shown in Fig. 11, the movements of any desired number of aircraft within a given area of a terminal or other flight announcing station are visually posted on a flight progress announcing board, shown in the lower right hand portion of the figure, preferably by means of rotatable indicators which are arranged in groups, such as the horizontal rows or tiers designated 0 to 9, each of which groups is identified with a certain flight and is adapted to display the flight identification number and flight information such as the time at which the aircraft passes or reaches a particular location or other marker point, generally referred to in the art as a fix, and the altitude of the aircraft at the various fix points, the indicators also being arranged in groups corresponding to the different fix points to which they relate, such as Fix-1, Fix-2 and Fix-3 illustrated. Such a flight progress announcing board, for example, may be located at an airway traffic control center, such as an airport where the flights terminate or traverse a predetermined area associated with the airport, and are posted by means of the foregoing indicators on the announcing board so as to be visible at all times to the airway traffic control personnel and also to passengers or others interested in the progress of the flights thus posted.

Usually, the flight plans in regard to the various aircraft, particularly the time at which the aircraft are to pass or arrive at various marker points and the altitude which the aircraft are to maintain at such points, are prepared in advance and are posted initially on the flight progress announcing board by a local operator. Each aircraft in flight, however, may encounter adverse weather or other conditions which necessitate a change in the planned time or altitude of the aircraft at the various marker points, at which time the radio operator in the aircraft thus affected may either telephone or telegraph the con-

ditions and new information to a remote control operator located at a station along the flight route, or may telegraph the new information directly to a radio receiving station located along the route, from which latter station the signals comprising the flight and fix identification and the new information in regard thereto are transmitted automatically to the traffic control station where they are temporarily stored and decoded and caused to select and operate the proper group or groups of indicators to display the new information.

More specifically, at the radio receiving station referred to above, which is tuned to receive the signals from the aircraft mentioned, the signals are retransmitted automatically over a communication circuit to the traffic control station where they are stored on a control form, as by a tape reperforator, and automatically retransmitted by a tape transmitter to the receiving equipment associated with the flight progress announcing board. Each of the tuned receiving circuits of the foregoing radio receiving station has a tape reperforator and tape transmitter associated therewith, and seeker mechanism common to the various tape transmitters is provided for causing the messages stored in the various tapes by the reperforators to be retransmitted in the proper order, each such message being made ready for retransmission by an end-of-message signal that accompanies the message. By means of this arrangement the information posted on the flight progress announcing board may be kept up to date by the signals transmitted by the radio operators of the various aircraft, without the intervention of the local operator.

Instead of having the radio operators in the aircraft transmit the information directly to the traffic control station, this information may be transmitted by a remote control operator located along the route who either personally observes the progress of the aircraft or receives the flight information from the aircraft in the manner above stated, and retransmits the desired information, as by means of a keyboard teleprinter, over a communication circuit to a tape reperforator which also has a tape transmitter associated therewith for retransmitting the information to the flight progress announcing board for selecting and actuating the proper indicators. Either method may be employed or both may be employed at the same time if desired, since the seeker mechanism hereinbefore referred to causes the messages stored in the various perforated tapes by the signals transmitted from the aircraft and also those transmitted by the remote control operator to be retransmitted to the traffic control station in proper sequence and without interfering with each other. The information thus transmitted either by the radio operator in an aircraft or by the remote control operator referred to above, includes the flight number and also a signal corresponding to the proper marker point or fix, and these signals automatically cause selection and operation at the flight progress announcing board of the proper row of indicators in the group associated with the proper fix designation, irrespective of the instant location of the posting level of the indicators on which the flight information with regard to the aircraft is to be displayed.

At the traffic control center a local operator has a keyboard and mechanism associated therewith for initially setting up information such as the flight designations and the estimated time and altitude of the various aircraft at the several fixes

or marker points, and also has means for changing the sequence or order of appearance of the various items of information thus posted so that if an aircraft either is delayed or is ahead of its planned schedule, the order or sequence in which the various items of information including the flight identification with respect to the different aircraft are displayed on the flight progress board may readily be changed so that these items appear in the new sequence in which the various aircraft traverse or land at the marker points. The local operator also has means for deleting the information posted on any horizontal row in regard to any particular aircraft in any particular fix group, so that after the aircraft has passed one or more of the marker points or has landed, or the flight is otherwise terminated, the information which is thus no longer needed may be removed in order to provide additional room for other flights. The local operator can, with one operation of the keyboard, cause the remaining items of information in regard to other aircraft to be transferred to new levels, including the level from which the information has been deleted, which transfer with regard to the other aircraft is automatically effected in response to the foregoing operation of the keyboard, and furthermore the order in which the remaining items of information previously have been posted may be caused to remain unchanged. Also, the local operator readily can reassign the groups of indicators to different fix designations to provide for expansion or contraction of the number of items which may be posted with regard to each particular marker point, and here again the sequence of the remaining items in any fix group may be caused to remain unchanged, or if desired, the sequence or order in which any one or more of the items are posted may readily be changed at will. The seeker mechanism above referred to cooperates with the signals transmitted by the local operator to insure that such signals will not interfere with the signals transmitted from the various aircraft or remote control ground stations.

In order to provide a permanent record of the various items of information received at the central control station from the various aircraft and remote control stations, a recording device such as a telegraph printer is connected in the circuit so that all of the flight designation, fix and flight information represented by the received signals may be printed to provide a permanent record of all the flights within the given area, and also to provide a convenient means for checking the information posted on the indicators. Various other functions which are also provided by the system, such as checking for improper signals and insuring that the incoming signals select and actuate the proper group of indicators, are described hereinafter in detail.

Referring now to the drawings specifically in which like numerals of reference are employed to designate like parts throughout the several views, there is shown on Figs. 1 to 7 thereof, a complete system according to a preferred embodiment of the invention. Fig. 1 shows a plurality of teleprinter mechanisms each comprising a transmitting keyboard for generating and transmitting electrical signals in accordance with the information to be transmitted and receiving mechanism for distributing these signals to reperforating devices controlled thereby. The operation of the reperforator mechanism causes the information received by the distributor to be stored in a perforated tape associated with each

reperforator mechanism. The keyboard teleprinters in the various flight information zones may be situated at remote points from the receiving mechanism such, for example, as airline radio offices, airport control towers, army and navy flight control headquarters, local airway traffic control communication centers, any point on the "B" network, any point on the airway traffic control communication teleprinter network, such as at range stations, radio beacons or markers, or the teleprinters may be situated within the aircraft. The teleprinters located at ground stations are connected to the receiving distributor by a channel of communication such as a telegraph line wire over which the signals are transmitted, as is well known in the telegraph art, by simplex method of transmission although it will be understood that multiplex transmission may be employed. The teleprinters situated within aircraft are each operatively connected to a radio transmitter carried by the aircraft whereby the pilot or assistant may operate the teleprinter during the time that the aircraft is in flight and thus transmit radio signals which are received by the radio receiving apparatus of Fig. 1 situated at any suitable location, the received signals controlling the operation of the distributing and reperforating mechanism to store the received signals on perforated tapes. Each radio teleprinter has associated therewith an audio frequency generator whereby the audio component of the radio signals transmitted comprises a predetermined frequency associated with each aircraft and differs, preferably, from the frequency of other aircraft having similar transmitting mechanism.

The radio receiving apparatus comprises a plurality of audio frequency filters, each associated with an aircraft and tuned to the frequency of the audio frequency generator of the associated aircraft.

Each filter circuit is associated with distributing and reperforating mechanism whereby messages may be received simultaneously from a plurality of aircraft in flight at any time and stored on perforated tapes regardless of whether other aircraft are transmitting messages at the time.

The specific arrangement shown on Fig. 1 employs a single radio frequency band for a plurality of radio transmitting teleprinters by employing suitable audio frequency generators and filters at the transmitting and receiving stations respectively. It will be understood, however, that different radio frequency bands may be employed for the different aircraft in flight, in which case the audio frequency generator and filter equipment and circuits will not be required.

Each message received by the distributor mechanism of Fig. 1 is followed by an end-of-message signal which is stored in the appropriate group of relays of Fig. 1 and causes the seeker mechanism to function and start an associated tape transmitter into operation to transmit the received message during a revolution of the distributor DR1 of Fig. 4, which is set into operation by the seeker relay associated with the operated group of end-of-message relays when the seeker mechanism has come to rest in a position associated with the operated seeker relay. Fig. 1 also shows a multiplex telegraph printer MP for recording information corresponding to the selection and posting signals received.

The groups of relays shown on Fig. 5 of the drawings, are employed to store and decode the message signals stored on the perforated tape,

two groups of these decoding relays being employed to store and decode the identification characters of a desired flight, one group being employed for the marker or fix information, one group for the range and two groups for the digit information.

Fig. 3 shows the announcing or bulletin board, hereinafter referred to as a flight progress board, comprising ten posting spaces or rows of electromagnetic indicator units for posting the identification, time and altitude of each flight or aircraft respectively. As more clearly shown on Fig. 9, the flight progress board is divided into marker or fix sections, each section comprising a plurality of groups of indicating devices. Fix 1, for example, comprises the groups of indicating devices of the fix posting or levels 7, 8 and 9, fix 2 the groups of indicating devices of levels 4, 5 and 6 and fix 3 the devices of levels 0, 1, 2 and 3. The specific relationship between the groups of devices and the fix designations is shown on Fig. 9 by way of example only in order that a clear understanding of the system may be obtained without unnecessary duplication or complication of the circuits and descriptive matter herein, whereas in practice it may be desirable to rearrange the groups of indicating devices classified in accordance with fix postings to provide for a greater or lesser number of fix sections of the board and a greater or lesser number of groups of indicating devices within the different fix sections. Fig. 3 also shows a pair of gang relays associated with each posting space as, for example, the relays G9 and GA9 associated with the posting space 9. The purpose of these relays will be more clearly apparent as the description proceeds.

The identification indicators associated with each posting space are each provided with a set of equally spaced contacts corresponding in number to the number of positions to which the indicating elements may be moved and arranged in a continuous series. A wiper arm is attached to the indicator drum assembly and engages the contacts of the indicator in accordance with the setting of the drum, for example, if the drum is set to display the digit 1, the wiper will be in engagement with contact 1; similarly, if the indicator is set to its blank position the associated wiper will be in engagement with its contact BL.

The wiper and contact assemblies herein referred to are illustrated schematically in arcuate form on Fig. 5 of the drawings to show more clearly the electrical circuits connected thereto. It will be readily apparent, however, that these wipers take settings in accordance with the settings of their associated indicators in accordance with the flight identification symbols posted on the progress board. There is also shown on Fig. 5, to the right of these identification wiper assemblies, a group of fix storage indicators designated FS0 to FS9 which are employed for storing information regarding the fix or marker section of the flight progress board within which a desired group of flight indicators is disposed. The purpose and function of these fix storage indicators will be set forth more in detail as the description proceeds.

There is shown on Fig. 6 of the drawings, two groups of storage indicators designated S1 and S2 having associated therewith the gang relays M1, A1 and M2, A2 respectively and a group of range relays designated IDENT, TIME and ALT for selecting for operation the corresponding indicators of a particular flight within a desired fix section of the flight progress announcing board. Fig. 6

also shows a transmitting distributor DR2 and a group of pulsing relays P1, P2, P4 and P7 connected thereto for generating indicator restoration and actuation impulses by means of which the indicators of Figs. 3 and 5 are actuated to their different settings under control of the digit signals stored on the relays of Fig. 5 or set up on the data keys of the keyset, as the case may be, to post the desired information.

Fig. 7 shows a sequence stepping switch and a group of sequence and control relays including transfer relays employed for the purpose of changing the sequence or order in which the information appears on the flight progress board, hereinafter referred to as sequencing. The circuit arrangement shown provides a system which is extremely flexible and in which the sequence operations are automatically accomplished by a single operation of the keyset of Fig. 2.

Fig. 2 shows a keyset comprising a group of six keys and groups of keys designated HORIZ, POS., CHANGE POS., DATA TENS and UNITS respectively. There is also provided a group of keys designated FS, SEQ, WO, IDENT, TIME and ALT, each of the keys in this group being arranged to remain in the operated position until released by the operation of the key release magnet KR. The keyset is located at the airway traffic control center or within the airport control tower, as the case may be, and preferably in a position such that the keyset operator is enabled to include the indicators of the flight progress board within his field of vision. The keyset is employed for setting up signals controlling the transmission of a message to be posted on the flight progress board classified according to fix and range characteristics of a desired flight. The keyset is also employed to change the order of appearance of the information posted, as for example, transposing the information posted on two adjacent rows of indicators or transferring the information posted on a row of indicators to the indicators of any other row and shifting the information posted on the intermediate rows of indicators, without disturbing the order of the intermediate information, either upwards or downwards in accordance with whether the information taken out of the first order of appearance on the flight progress board is to be transferred to a higher or lower level. This operation is referred to herein as sequencing. In addition to the foregoing, the keyset is employed to wipe out the display on the indicators of the flight progress board. The performance of any of these keyset operations includes the operation of one of the keys FS, SEQ, WO, IDENT, TIME and ALT which causes the seeker of Fig. 1 to come to rest on a set of terminals associated with the keyset and start the distributor DR2 in operation to cause the selected indicators to take their new settings to post the desired flight information in the selected posting spaces.

From the foregoing, it will be noted that posting signals may be received from a keyboard transmitter located at a ground station at a distance from the receiving station, from an aircraft in flight, and from a local keyset. Means are provided at the receiving station for storing these signals until a seeker mechanism has operated to cause the stored signals to be effective in causing the information represented thereby to be posted on the flight progress board.

Posting the board by incoming signals

The manner in which signals received from the teleprinter 1, Fig. 1, over the line L are employed

to control the operation of the flight progress board, Figs. 3 and 9, and the monitor printer MP, Fig. 1, will now be described.

Assume, by way of example, that the flight progress board is located at the Washington Airport and that the sections of the board designated Fix 1, Fix 2 and Fix 3 represent the designations CAMDEN, BALTIMORE and WASHINGTON airports respectively and furthermore that the time of day is 1:15 P. M. Assume, further, that the operator desires to transmit to the Washington airport from his keyboard teleprinter 1 located, for example, at the Camden fix or marker point, information that the flight 34 is scheduled to pass over the Camden fix at 1:35 P. M. at an altitude of 4500 feet which information will be printed on the multiplex printer MP and posted on the flight progress announcing board at the Washington airport.

The operator at Camden actuates the keys of his teleprinter keyboard in the following order: 3 4 1 3 3 5 space space 3 4 1 2 4 5 £. The first two keys 3 and 4 of the keys depressed represent the flight identification number, the third key 1, the fix number, corresponding to Camden, the fourth key 3, the range TIME, the fifth and sixth keys 3 and 5, the tens and units digits respectively of time and the two operations of the space bar represent a spacing signal between the first and second part of the message to be transmitted. The keys 3 and 4 following the space signal represent the flight identification number, the key 1 the fix number, the key 2 the range ALT, the keys 4 and 5 the thousands and hundreds digits of the altitude and the key designated £ is employed to transmit the end-of-message signal.

The keyboard printer may be one of any of the well known types such as, for example, what is known in the art as a 2B printer that records the signals on a tape in response to start-stop or simplex type signals, such signals being composed of marking and spacing line conditions comprising a start impulse followed by groups of permutations of five intelligence impulses in various combinations representing the characters to be transmitted or received and each group being terminated by a rest impulse which is of opposite line condition to that of the start impulse. The actuation of any of the keys of the associated keyboard causes the transmission of signals representing the character assigned to each key.

The operation of the flight identification key 3 causes a start impulse to be applied to the line L, thereby setting the distributor 2 into operation. This impulse is followed by a five unit code permutation signal having the code unit 1 thereof marking and the code units 2, 3, 4 and 5 spacing in character, Fig. 8, followed by a rest impulse.

The operation of the distributor 2 causes the code units 1, 2, 3, 4 and 5 of the intelligence signal to be transmitted to the tape reperforator 3 over the conductors 4, 5, 6, 7 and 8 respectively. When this has been accomplished an impulse is transmitted by the distributor over conductor 9 to cause the reperforator to perforate the tape 11 issuing therefrom in accordance with the signals received and step the tape ahead into position for the next succeeding perforating operation corresponding to the second digit of the flight identification number. Since the permutation signal for the digit 3 has the code unit 1 only marking in character, conductor 4 is energized and conductors 5, 6, 7 and 8 are deener-

gized thereby causing a single perforation corresponding to the code unit 1 to be made in the tape at this time.

Conductors 4, 5, 6, 7 and 8 are connected by way of conductors 1, 2, 3, 4 and 5 of cable 12 to the windings of the end-of-message relays EM1, EM2, EM3 and EM4, conductors 1 and 2 of cable 12 being connected to the windings of relay EM1 and conductors 3, 4 and 5 of cable 12 being connected to the windings of the relays EM2, EM3 and EM4 respectively. Energization of conductor 4 causes relay EM1 to operate by way of conductor 1 of cable 12. Relay EM1 locks by way of its make contact and armature 13 to battery on conductor 14 supplied by the break contact of the sixth pulse relay 20 of the distributor 2. The operation of relay EM1 is without effect at this time, relay EM1 releasing upon the subsequent operation of the sixth pulse relay.

In a similar manner the signals corresponding to the digits 4, 1, 3, 3 and 5 are received and stored in the perforated tape 11, the relays EM1 to EM4 operating in code combination each time a digit signal is received. The two space signals immediately following the digit 5 signal cause the tape to be stepped ahead twice without perforating intelligence signals therein. Signals corresponding to the digits 3, 4, 1, 2, 4 and 5 respectively follow the space signals and are stored in the tape 11 and also cause the operation of the end of the message relays EM1 to EM4 in code combination corresponding to each of the digits stored in the tape.

Immediately following the signal for the digit 5 is the end-of-message signal which, in the assumed example, is the signal for f having code units 1, 2 and 4 spacing and units 3 and 5 thereof marking in character. This signal causes relays EM2 and EM4 to operate and lock to battery on conductor 14 and relays EM1 and EM3 to be unoperated. Ground at armature 15 and break contact of relay EM1 is extended to armature 16 and make contact of relay EM2, armature 17 and break contact of relay EM3, armature 18 and make contact of relay EM4 and thence by way of conductor 19 to the winding of relay L and thence to battery, thereby causing relay L to operate and lock by way of its make contact and armature 21, conductor 22, break contact and armature 23 of relay RS5 to ground. Conductor 22 is connected to conductor 24 extending to contacts 25 of the auto-control AC which, when a complete message is stored in the tape loop between the reperforator and tape transmitter 26, are in engagement with each other thereby applying ground to the locking circuit of the relay L and holding relay L operated.

The operation of relay L at its armature 27 interrupts the circuit to terminals 3 and 7 of the bank A of the seeker switch and at the make contact of armature 27 of relay L applies ground to the corresponding armatures 27 of the relays K, R1 and R2 and thence by way of the break contact of relays K, R1 and R2 to terminals 1, 2, 4, 5, 6 and 8 of bank A of the seeker switch. If it be assumed that the switch wipers are resting on their terminals 1 at this time, ground at terminal 1 is extended by way of the switch wiper of bank A, break contact and armature 28 of the seeker stepping magnet SSM and thence to battery, thereby causing the stepping magnet to operate on self interruptions and advance the wiper A thereof to its terminal 3 which has ground removed therefrom by the operation of relay L.

With the wipers of the switch SSM resting on their terminals 3, a circuit is completed from battery at armature 29 and make contact of relay L, conductor 31, winding 1 of relay TC, conductor 32, terminal 3 of bank C of the seeker switch and wiper thereof, conductor 34, winding of the start magnet SM1 of the distributor DR1, Fig. 4, conductor 35, segment 1 of the ring R1 of the distributor DR2, Fig. 6, brush DB1 to grounded ring R2, thereby causing relay TC to operate and connect the transmitting tongues of the tape transmitter 26 to the selection magnets of the multiplex printer MP and to the distributor DR1. Relay TC locks from battery by way of its winding 2 and contacts 37, conductor 38, break contact and armature 39 of relay REL, Fig. 7, to ground.

The start magnet SM1 operates in series with relay TC thereby attracting the latch 41 and setting the distributor DR1 into operation. The engagement of brush B1 of the distributor DR1 with segment 2 of ring R1 closes a circuit from tongue 1 of the tape transmitter 26, also designated TTR1, contacts 42 of relay TC, conductor 1 of cable 43, segment 1 of ring R2 of the distributor DR1, brush B1, segment 2 of ring R1, conductor 1 of cable 44, winding of relay II1 to ground. Since, in the example assumed, the first digit of the flight identification number is the digit 3, the transmitting tongue 1 of the tape transmitter TTR1 is in the closed position, thereby applying battery through resistance 45 to the circuit just described and causing relay II1 to operate. Relay II1 locks by way of its contact and armature 46, conductor 2 of cable 47, break contact and armature 48 of release relay REL and thence to ground.

The engagement of segment 2 of ring R3 of the distributor DR1 by the brush B2, closes a circuit from the tongue 2 of the tape transmitter TTR1 through contact 49 of relay TC, conductor 2 of cable 43, segment 1 of ring R4, brush B2, segment 2 of ring R3, conductor 1 of cable 44 to the winding of the first digit identification relay II2. Relay II2 does not operate, however, as the tongue 2 of the tape transmitter is prevented by the tape 11 from engaging its transmitting contact. In a similar manner circuits are completed from tongues 3, 4 and 5 of the tape transmitter TTR1 by way of conductors 3, 4 and 5 of cable 43, brushes B3, B4 and B5 and their associated segments 2 of rings R5, R1 and R9, conductors 13, 19 and 25 of cable 44 to the windings of relays II3, II4 and II5 respectively. These relays are prevented from operating at this time by the tape 11 maintaining the tongues 3, 4 and 5 of the tape transmitter disengaged from their associated contacts. The digit 3 has now been transferred from the perforated tape 11 to the group of first digit identification relays II1 to II5 and stored therein under control of the release relay REL.

As the brushes of the distributor DR1 are disengaged from segment 2 of rings R1, R3, R5, R7 and R9, the circuits between the tongues of the tape transmitter TTR1 and the group of first digit identification storage relays are interrupted. As segment 2 of ring R11 of the distributor DR1 is engaged by the brush B6, battery at segment 2 of ring R12 is applied by way of brush B6, segment 2 of ring R11, conductor 6 of cable 43, contact 51 of relay TC to the tape step magnet TS of the tape transmitter TTR1, the circuit continuing through resistance 52 to ground thereby causing the tape step magnet

TS to operate and step the tape perforations corresponding to the second identification digit 4 into alignment with the feeler pins associated with the tape transmitter tongues.

It will be noted that conductors 1, 2, 3, 4 and 5 of cable 43 are extended to the selection magnets SM1, SM2, SM3, SM4 and SM5, respectively, the opposite end of the windings of these selection magnets being connected to ground. With this arrangement the operation of the tape transmitter tongue 1 in response to the first digit 3 of the flight identification number causes the selection magnet SM1 of the multiplex printer MP to operate in parallel with relay 111.

The engagement of segment 2 of the ring R11 by the brush B6 applies battery to conductor 6 of cable 43 extending to the print magnet PM of the multiplex printer, the circuit continuing to ground thereby causing the print magnet PM to operate and the printer to record the digit 3. When the bush B6 moves off segment 2 of ring R11, battery is removed from conductor 6 of cable 43 and the print magnet PM and tape step magnet TS release.

As the brushes of the distributor DR1 move into engagement with their segments 4 of rings R1, R3, R5, R7 and R9, the tongues of the tape transmitter TTR1 are connected by way of conductors 2, 8, 14, 20 and 26 of cable 44 to the windings of the second digit identification storage relays 211 to 215, Fig. 5. This group of storage and decoding relays is identical with the first digit relays 111 to 115 and for this reason are indicated in diagrammatic form by the rectangle 30. Referring to Fig. 8 it will be noted that the digit 4 corresponding to the second digit of the identification number has the code units 2 and 4 marking and units 1, 3 and 5 thereof spacing in character. The tongues 2 and 4 of the tape transmitter TTR1 will, therefore, be in engagement with their associated contacts and apply battery to conductors 2 and 4 of cable 43 extending to rings R4 and R8 and thence by way of brushes B2 and B4 to segment 4 of rings R3 and R7, conductors 8 and 20 of cable 44 to cause the associated second digit storage relays 212 and 214 to operate and lock to conductor 2 of cable 47 to which battery is applied by armature 48 and break contact of relay REL. The second digit 4 is now stored in the storage and decoding relays 21 of Fig. 5, the selection magnets SM2 and SM4 of the monitor printer operating at this time to store the digit 4 within the printer.

As brush B6 of the distributor DR1 moves into engagement with segment 4 of ring R11, battery at ring R12 is applied to conductor 6 of cable 43 to cause the operation of the print magnet PM of the printer and the tape step magnet TS of the tape transmitter TTR1, thereby printing the digit 4 and advancing the tape 11 whereby the next group of tape perforations corresponding to the fix digit 1 are brought into operative engagement with the feeler pins of the tape transmitter.

As segment 6 of rings R1, R3, R5, R7 and R9 are engaged by their respective brushes, battery is applied to conductors 3, 9, 15 and 21 of cable 44 thereby causing the operation of fix relays F1, F2, F3 and F5 to store the fix digit 1 now set up by the tongues of the tape transmitter TTR1. These fix relays lock by way of their contacts and armatures 53 to battery on conductor 2 of cable 47. The engagement of segment 6 of ring R11 by the brush B6 applies battery to conductor 6 of cable 43 thereby caus-

ing the multiplex printer to print the digit 1 set up therein by the selection magnets SM1, SM2, SM3 and SM5 which operated in parallel with the fix relays F1, F2, F3 and F5, respectively.

5 Battery on conductor 6 of cable 43 causes the tape 11 to be stepped ahead with the code combination 3 corresponding to the range TIME in alignment with the feeler pins of the transmitter. This signal has the code unit 1 marking and the units 2, 3, 4 and 5 thereof spacing in character, Fig. 8.

The engagement of segment 8 of the distributor rings by the brushes B1 to B5 applies battery to conductor 4 of cable 44, thereby operating 15 range relay R1 which locks by way of its armature 60 to conductor 2 of cable 47 thereby storing the range signal TIME in the range decoding relays. The selection magnet SM1 is also operated to store the digit signal within the telegraph printer MP. When brush B6 engages segment 8 of ring R11 the digit 3 corresponding to the range TIME is printed by the multiplex printer and the tape 11 is stepped ahead to the tens data position.

The tens digit 3, it will be recalled, has the 25 code unit 1 marking and the code units 2, 3, 4 and 5 spacing in character and battery is applied, therefore, by the tape transmitter, to conductor 1 only of cable 43. When brush B1 engages terminal 10 of the ring R1, battery is applied to conductor 5 of cable 44 thereby operating relay DT1 which locks by way of its armature 54 to battery on conductor 2 of cable 47. The selection magnet SM1 of the printer is also operated to store the tens data digit 3. When segment 10 30 of ring R11 is engaged by brush B6, battery on conductor 6 of cable 43 causes the printer to record the digit 3 corresponding to the first digit of the time information and the tape 11 to be stepped ahead to the data units position.

With the data units digit 5 in position within the tape transmitter TTR1, battery is applied to conductor 5 of cable 43 by the transmitter tongue 5 thereby causing the operation of the printer selection magnet SM5. When brush B5 engages segment 12 of ring R9 battery is applied to conductor 30 of cable 44 extending to the units digit relay DU5, causing relay DU5 to operate and lock to battery on conductor 2 of cable 47. The units digit relays are similar in all respects to the tens digit relays DT1 to DT5 and for this reason are indicated in diagrammatic form by the rectangle 55. It will be understood that the conductor 6 of cable 44 is extended to the winding of relay DU1 and the conductors 12, 18, 24 and 30 of cable 44 extend to the windings of relays DU2, DU3, DU4 and DU5 respectively, each of these relays upon operation locking to battery at the break contact and armature 48 of relay REL by way of conductor 2 of cable 47.

When brush B6 engages segment 12 of ring R11, the digit 5 is printed by the multiplex printer and the tape 11 is stepped ahead. In the assumed example, it will be recalled, the time data 3 5 is followed by two space signals and, therefore, none of the conductors 1 to 5 of cable 43 are now connected to battery except conductor 3 which causes the operation of the selection magnet SM3 of the multiplex printer to store the space signal therein.

The signals for the flight identification number 34, fix 1 (Camden), time range 3, and time digits 3 5 are now stored in the groups of relays of Fig. 5 and printed on the printer MP. The manner in which these stored signals control the selection and operation of the time indicator

units within the board section, Fix 1 associated with flight number 34 and actuate the same to post the stored time information will now be described.

Referring now to Fig. 9 of the drawings, the flight number 34 is shown posted in positions or levels 8, 6 and 3 associated with the Fix sections 1, 2 and 3 of the flight progress board, these Fix sections in the example assumed corresponding to Camden, Baltimore and Washington Airports respectively. The time indicators for the flight 34 associated with the Camden Fix 1 are located in position 8. As the distributor brushes B1 and B2 pass over segments 13 to 22 of rings R1 and R3, a circuit is closed in part to each of the gang relays GA0 and GA1 to GA9 successively until the gang relay associated with the desired group of indicators is selected. More specifically, when the brush B1 engages segment 13 of ring R1, a circuit is closed in part to operate the gang relay GA0 and when brush B1 engages segment 14 of ring R1 a circuit is closed in part to operate the gang relay GA1 and as each succeeding segment of ring R1 is traversed by the brush B1, circuits are closed in part to the windings of relays GA2, GA3, GA4, GA5, GA6 and GA7.

When the brush B1 engages segment 21 of the ring R1, relay GA8, Fig. 3, associated with the indicators of position 8 of the flight progress board, is operated over the following circuit: Grounded armature 56, and make contact of relay 111, armature 57 and break contact of relay 112, armature 58 and break contact of relay 113, armature 59 and break contact of relay 114, armature 61 and break contact of relay 115, conductor 3 of cable 62, terminal 3 and wiper of indicator IT8 of position 8, conductor 8 of cable 63, segment 21 of ring R1 of the distributor DR1, brush B1, segment 10 of ring R2, conductor 8 of cable 64, wiper of indicator unit IU8 of position 8 and terminal 4 thereof, conductor 4 of cable 65, and thence through break contacts of second digit identification relays 1, 3 and 5 and make contacts of second digit relays 2 and 4, conductor 66, armature 67 and make contact of fix relay F1, armature 68 and make contact of relay F2, armature 69 and make contact of relay F3, armature 71 and break contact of relay F4, armature 12 and make contact of relay F5, conductor 1 of cable 73, terminal 1 and wiper of fix storage indicator FS8, conductor 8 of cable 74, segment 21 of ring R3, brush B2, segment 10 of ring R4, conductor 8 of cable 75, winding of relay GA8 to battery. Relay GA8 locks by way of its contact 76, conductor 11, contact 78 of relay TC, conductor 38, break contact and armature 39 of relay REL to ground.

When brush B6 engages segment 14 of ring R11, ground at segment 4 of ring R12 is applied by way of brush B6, segment 14 of ring R11, conductor 79 to the winding of start magnet SM2 of distributor DR2, the circuit continuing to battery, thereby causing the start magnet SM2 to operate and withdraw the latch 81 from the path of the brush DB1 and thus set the distributor DR2 into operation. Segment 14 of ring R11 is of sufficient length to insure that the brush DB1 of the distributor DR2 has moved out of engagement with segment 1 of the ring R1, thereby removing ground from conductor 35 and causing the release of the start magnet SM1 of the distributor DR1 before the distributor DR1 has completed its revolution, whereby the latch 41 releases and arrests the brushes of the distributor DR1 at the completion of their revolution.

When brush B6 passes off segment 14 of ring R11, ground is removed from conductor 79 thus releasing the start magnet SM2 and causing the brush DB1 of the distributor DR2 to come to rest at the completion of one revolution thereof.

As brush DB1 engages segment 2 of the distributor DR2 ground is applied to conductor 82 extending to the winding of relay ST, thereby causing relay ST to operate. When brush DB1 leaves segment 2 of the ring R1, relay ST releases. When the brush DB1 engages segment 4 of the ring R1, battery is applied to conductor 80 extending to the winding of pulsing relay P1, the circuit continuing to battery, thereby causing relay P1 to operate and transmit the first restoration impulse to the selected indicators. When the brush B1 of the distributor DR1 was brought into engagement with segment 8 of ring R1, relay R1, it will be recalled, operated and locked by way of its armature 60 to conductor 2 of cable 47. The operation of relay R1 at its armature 83 and make contact thereof applies ground to armature 84 and break contact of relay R2, armature 85 and break contact of relay R3, armature 86 and break contact of relay R4, armature 87 and break contact of relay R5, conductor 6 of cable 88 extending to the winding of the range relay TIME thereby causing relay TIME to operate and select the time indicators of the posting board for operation in accordance with the particular level or position of these indicators controlled by the selected gang relay GA which, in the assumed example, is the gang relay GA8.

With relay P1 operated in response to the engagement of segment 4 of the ring R1 by the brush DB1, a circuit is closed from battery at armature 89 and break contact of relay AG, conductor 4 of cable 91, make contact and armature 92 of relay P1, conductor 93, make contact and armature 94 of relay TIME, conductor 95, winding and switch contact 96 of indicator TT8, conductor 3 of cable 97, contact 98 of relay GA8, to ground, thereby operating the indicator IU8 in response to the first restoration impulse applied thereto. The indicator TU8 also receives a restoration impulse at this time over the following circuit: Battery at armature 99 and break contact of relay AG, conductor 4 of cable 101, make contact and armature 102 of relay P1, conductor 103, make contact and armature 104 of relay TIME, conductor 105, winding and switch contact 106 of indicator TU8, conductor 4 of cable 97, contact 107 of relay GA8 to ground. As brush DB1 moves off segment 4 of the ring R1, pulsing relay P1 releases and at its armatures 92 and 102 interrupts the restoration impulse to the indicators TT8 and TU8 respectively, thereby stepping the indicators ahead one step towards their blank or home positions by this restoration impulse.

Nine additional restoration impulses are transmitted by the relay P1 as the distributor brush DB1 engages segments 6, 8, 10, 12, 14, 16, 18, 20 and 22 of the ring R1 thereby causing the selected indicators TT8 and TU8 to be restored from their previous settings to their blank positions, each of the indicators being unresponsive to additional restoration impulses, if any, when in the blank position due to the interruption of their pulsing circuits by the switch contacts 96 and 106 respectively which are disengaged from each other when the indicators are at their blank settings.

The time and altitude posting indicators and the indicators of groups S1 and S2 are of a general type described in Patent 2,189,581 for Indicating device, granted February 6, 1940 to Raymond M.

Hicks and Merton L. Haselton, whereas the flight identification number and fix storage indicators are of a general type disclosed in Patent 2,155,825 for Numerical comparator, granted April 25, 1939 to Merton L. Haselton and Raymond M. Hicks.

When the brush DB1 engages segment 5 of ring R1, ground is applied to conductor 1 of cable 109, extending to the winding of relay RS5, Fig. 1. Relay RS5 does not operate at this time, however, as the end-of-message signal perforated in the tape 11 has not yet been received by the seeker release relays RS1 to RS4.

As brush DB1 moves into engagement with segment 1 of ring R1, ground is applied to the winding of relay PTR causing relay PTR to operate and at its armature 111 and make contact thereof, apply battery to conductor 2 of cable 109 extending to the print magnet PM of the multiplex printer. Since, as will be recalled, the selection magnet SM3 thereof operated to store a space signal within the printer, the operation of the print magnet merely creates a space in the printed message. As the brush passes off segment 1 of the ring R1, relay PTR and the print magnet release. It will be noted that conductor 2 of cable 109 is connected to conductor 6 of cable 43, thereby causing the tape step magnet TS of the tape transmitter TTR1 to be operated in parallel with the print magnet of the printer and step the tape ahead to its next position within the tape transmitter.

When brush DB1 engages segment 13 of ring R1, ground is applied to the winding of the relay SP, causing it to operate and at its armature 112 and make contact thereof apply battery to conductor 3 of cable 109 and thence to the selection magnet SM3 of the printer to insure that a space signal will be stored therein. When brush DB1 moves off segment 13 of the ring R1, relay SP releases and as the brush DB1 moves into engagement with segment 15 of the ring R1, relay PTR again operates causing the printer to insert a second space within the message printed and the tape transmitter to step the tape ahead to the next position corresponding to the first digit of the flight identification number which is now in position to be transmitted by the tape transmitter.

When the brush DB1 passes off segment 15 of the ring R1, relay PTR releases and removes battery from conductor 2 of cable 109 thus causing the release of the print magnet and the tape step magnet. As segment 24 of the ring R2 is traversed by the brush DB1, ground is applied to conductor 113, winding of relay AG, from whence the circuit is continued by the way of conductor 114, break contact and armature 115 of relay SEQ to battery. Relay AG operates and locks by way of its make contact and armature 116, conductor 1 of cable 47, break contact and armature 117 of relay REL to ground. The operation of relay AG at its armatures 89 and 99 removes battery from conductor 4 of cables 91 and 101 respectively and at its armatures 118, 119, 120, 121, 122 and 123, applies ground to conductors 1 to 6 of cable 124 extending to contacts of relays G0 to G9. Relay AG at its armature 125 and make contact thereof applies ground to conductor 126 extending to contact 127 of the gang relays GA0 to GA9. This circuit is continued through operated contact 127 of relay GA8 to the winding of relay G8 causing relay G8 to operate and at its contacts 128 to 133 close circuits by way of conductors 1 to 6 of cable 134 to the windings of the indicators of the level 8, these circuits being

connected to ground at operated contacts of the relay AG, thereby to condition the indicators of level 8 for operation by actuation impulses received from the group of pulsing relays P1, P2, P4 and P7, as the distributor DR2 continues its operation. The manner in which these circuits are employed to cause the time indicators TT8 and TU8 to be actuated from their blank settings to display the digits 3 and 5 respectively will not be described.

As the distributor brush DB1 passes over the group of segments 26 to 44 of the ring R1, a single impulse may be generated from relay P1, two impulses from relay P2, four impulses from relay P4 and seven impulses from relay P7. If an indicator is to be set to display the digit 1, the relay P1 only is employed, if the digit 2 is to be displayed relay P2 only is employed, relays P1 and P2 being employed to display the digit 3. The digit 4 is selected for display on an indicator by the relay P4, the digit 5 by the relays P1 and P4, the digit 6 by relays P2 and P4. When the digit 7 is to be displayed, relay P7 alone is employed. The digit 8 is obtained from a combination of impulses received from relays P1 and P7, the digit 9 from relays P2 and P7 and the digit 0 from the relays P1, P2 and P7. In the example assumed, the tens and units of the time information to be displayed correspond to the digits 3 and 5 respectively. The setting of the time tens indicator TT8 to display the digit 3 will first be described.

Referring now to Fig. 5, the settings of the relays DT1, DT2, DT3, DT4 and DT5 in response to the digit 3 establishes circuits from battery at the armature of relay DT1 by way of conductors 1 and 2 of cable 91 to pulsing contacts of relays P1 and P2 as follows: Battery at armature 135 and make contact of relay DT1, armature 136 and break contact of relay DT4, armature 137 and break contact of relay DT2, armature 138 and break contact of relay DT3, break contact and armature 139 of relay DT5, conductor 2 of cable 91 and thence to contact 141 associated with armature 142 of relay P2. A circuit is also closed from battery at armature 135 and make contact of relay DT1, armature 136 and break contact of relay DT4, armature 143 and break contact of relay DT2, armature 144 and break contact of relay DT3, break contact and armature 145 of relay DT5, conductor 1 of cable 91 to contact 146 associated with armature 147 of relay P1. Armature 147 of relay P1 and armature 142 of relay P2, are connected together by conductor 93.

When brush DB1 engages segment 26 of the ring R1 of the distributor DR2, relay P1 operates and applies battery at its contact 146 by way of its armature 147 to conductor 93, make contact and armature 94 of relay TIME, conductor 95, winding of indicator TT8, conductor 3 of cable 134, contact 130 of relay G8, conductor 3 of cable 124, armature 120 and make contact of relay AG to ground thereby causing indicator TT8 to be actuated in response to the first actuation impulse received. As the distributor brush moves out of engagement with segment 26 of the ring R1, relay P1 releases and interrupts the circuit to the indicator TT8 thereby causing the indicator to step ahead to display the digit 1.

When the brush moves into engagement with segment 28 of the ring R1, ground is applied to relay P2 which operates and applies battery at its contact 141 by way of armature 142 to conductor 93 to operate the indicator TT8 over

the circuit just described. As the brush moves off of segment 28 relay P2 releases and interrupts the circuit to indicator TT8 causing the indicator to step ahead to display the digit 2.

As segment 30 of the ring R1 is engaged by the brush DB1, relay P2 again operates causing the indicator TT8 to be actuated. As the brush passes off segment 30, relay P2 releases and interrupts the circuit to indicator TT8 which now steps ahead to display the digit 3 stored in the tens digit relays DT1 to DT5. No additional impulses are transmitted to this indicator as the distributor continues its operation for the reason that battery is applied to conductors 1 and 2 only of cable 91 by the instant setting of the tens digit storage relays.

The digit 5 having the code unit 5 thereof marking and codes 1, 2, 3 and 4 spacing has been stored, it will be recalled, in the units digit storage relay group 55, Fig. 5, relay DU5 being operated and relays DU1 to DU4 being released. This setting of the DU relays applies battery to conductors 1 and 3 of cable 101 extending to contacts 140 and 148 of relays P1 and P4 respectively. Since the relays DU are identical with the relays DT, the circuit to their contacts will be described by reference to relays DT as, for example, the circuit to conductor 1 of relay 101 is as follows: Battery at armature 135 of relay DU1 and break contact thereof, armature 149 and break contact of relay DU2, armature 151 and break contact of relay DU3, armature 152 and break contact of relay DU4, make contact and armature 145 of relay DU5, conductor 1 of cable 101 and thence to contact 140 of relay P1. The circuit to conductor 3 of cable 101 may be traced from battery at armature 153 and break contact of relay DU1, armature 154 and break contact of relay DU2, armature 155 and break contact of relay DU3, armature 156 and make contact of relay DU5, armature 157 and break contact of relay DU4, conductor 3 of cable 101 and thence to contact 148 of relay P4. The operation of relay P1 in response to the engagement of segment 26 of the ring R1 by the brush DB1 applies battery at contact 140 and armature 158 of relay P1 to conductor 103, make contact and armature 104 of relay TIME; conductor 105, winding of indicator TU8, conductor 4 of cable 134, contact 131 of relay G8, conductor 4 of cable 124, armature 121 and make contact of relay AG to ground, thereby causing the indicator TU8 to operate to display the digit 1.

When the brush DB1 engages segments 33 of ring R1, relay P4 operates and applies battery at contact 148 and armature 159 of relay P4 to conductor 103 to step the indicator TU8 ahead to display the digit 2. As the distributor brush DB1 passes over segments 35, 37 and 39, three additional impulses are applied by the relay P4 to the conductor 103 to cause the indicator TU8 to step ahead to display the digit 5. As the distributor brush passes over the even numbered segments 32 to 44, relay P1 closes its contact seven times without effect as battery is removed from the contacts of relay P1 at this time.

As segment 45 of the ring R1 is engaged by the brush DB1, ground is applied to conductor 161 thereby causing the operation of the release relay REL. The operation of relay REL at its armature 117 removes ground from conductor 1 of cable 47, thereby releasing relay AG. Relay REL at its armature 48 removes battery from conductor 2 of cable 47 thereby releasing the storage and decoding relays of Fig. 5. The re-

lease of relay R1 releases the relay TIME. The operation of relay REL at its armature 39 removes ground from conductor 38 thereby releasing relays TC, GA8 and G8. As the brush DB1 passes off segment 45 of the ring R1, relay REL releases. The distributor brush DB1 continues to rotate until arrested by the latch 81 with the brush in contact with segment 1 of ring R1. The time indicators corresponding to flight number 34 now post the number 35 corresponding to the time when the passage of the aircraft identified as flight 34 is scheduled to pass over the Camden marker.

The distributors DR1 and DR2 have each completed one revolution and the information corresponding to the incoming signals controlling this portion of the flight message has been printed by the multiplex printer. The seeker switch, however, is not released at this time, relay L 20 remaining locked to ground at the break contact and armature 23 of relay RS5, which does not operate until the end-of-message signal has passed through the tape transmitter.

With the brush DB1 resting on segment 1 of the ring R1 of the distributor DR2, a circuit is closed from grounded ring R2, brush DB1, segment 1 of ring R1, conductor 35, winding of start magnet SM1 of the distributor DR1, conductor 34, wiper and terminal 3 of level C of the seeker switch, conductor 32, winding 1 of relay TC, conductor 31, make contact and armature 29 of relay L to battery, thus causing the operation of relay TC and the start magnet SM1. The operation of start magnet SM1 attracts the latch 41 and sets the distributor DR1 into operation. As the even-numbered segments 2 to 12 of rings R1, R3, R5, R7 and R9 are traversed by their respective brushes, the flight identification number 34, fix 1, altitude range 2 and the altitude digits 45 are stored in the decoding relays of Fig. 5 and printed on the monitor printer, the printing and tape stepping operations being controlled by the passage of the brush B6 over the even-numbered segments 2 to 12 of ring R11. The engagement of segment 12 of ring R11 by the brush B6 causes the end-of-message signal to be stepped into the tape transmitter TTR1. This signal, it will be recalled, has the code units 3 and 5 thereof marking and the code units 1, 2 and 4 spacing in character.

The transmitter tongues 1, 2, 3, 4 and 5 are connected by way of conductors 1, 2, 3, 4 and 5 of cable 162 to the windings of seeker release relays RS1, RS2, RS3 and RS4. With the end-of-message signal in position within the tape transmitter TTR1, battery is connected to conductors 3 and 5 of cable 162 thereby operating the seeker-release relays RS2 and RS4 and applying battery to the winding of relay RS5.

As the distributor brushes engage segments 21 of rings R1 and R3, relay GA8 operates and locks by way of its contacts 76 to ground at the break contact and armature 39 of relay REL.

The range signal ALT having the code units 1, 2 and 5 thereof marking and the code units 3 and 4 spacing in character causes the operation of relays R1, R2 and R5. A circuit is completed from grounded armature 83 of relay R1, armature 84 and make contact of relay R2, armature 163 and break contact of relay R3, armature 164 and break contact of relay R4, armature 165 and make contact of relay R5, conductor 5 of cable 88, winding of relay ALT to battery, causing the range selection relay ALT to operate and close,

in part, pulsing circuits for the altitude indicators of the selected flight and fix.

The engagement of segment 14 of the ring R1 by the brush B6 applies ground to conductor 79, thereby operating the start magnet SM2 and setting the distributor DR2 into operation. The brushes of distributor DR1 are brought to rest by the latch 41 at the completion of their revolution, the start magnet SM1 associated therewith having released as the brush DB1 of the distributor DR2 passes off segment 1 of ring R1.

As the brush DB1 engages segments 2 and 23 of the ring R1, relay ST operates but performs no useful function at this time. When brush DB1 traverses segments 4 of the ring R1, relay P1 operates to transmit the first restoration impulse to the selected indicators over the following circuit: Battery at armature 89 and break contact of relay AG, conductor 4 of cable 91, make contact and armature 92 of relay P1, conductor 93, make contact and armature 166 of relay ALT, conductor 167, winding of indicator AT8, and switch contact 168 thereof, conductor 5 of cable 97, contacts 169 of relay GA8 to ground. Battery at armature 99 and break contact of relay AG, conductor 4 of cable 101, make contact and armature 102 of relay P1, conductor 103, make contact and armature 171 of relay ALT, conductor 172, winding of indicator unit AU8 and switch contact 173 thereof, conductor 6 of cable 97, contacts 174 of relay GA8 to ground. As the even-numbered segments 4 to 22 of ring R1 are traversed by the brush DB1, ten restoration impulses are transmitted to the indicators AT8 and AU8 to restore them to their blank settings.

As brush DB1 engaged segment 5 of the ring R1, ground was applied to conductor 1 of cable 109, extending to the winding of the seeker release relay RS5 from whence the circuit is continued by way of make contact and armature 175 of relay RS4, break contact and armature 176 of relay RS3, make contact and armature 177 of relay RS2, break contact and armature 178 of relay RS1 to battery, thereby causing relay RS5 to operate and at armature 23 thereof remove ground from conductor 22 causing relay L to release. The release of relay L at its armature 27 removes ground from armature 27 of relays K, R1 and R2 and its break contact closes a circuit from armature 27 of relay L to contacts 3 and 7 of the A level of the seeker switch, thereby releasing the seeker switch and establishing circuits thereto whereby the switch may be selectively operated by self-interruptions of the stepping magnet SSM to different positions in accordance with complete message information stored on any of the perforated tapes of Fig. 1 or the keyset of Fig. 2. When relay L releases the seeker switch is not stepped ahead but remains with the wipers thereof in contact with their terminals 3 until another complete message has been received.

When brush DB1 engages segment 7 of ring R1, relay PTR operates and applies battery to conductor 2 of cable 109, thereby printing the end-of-message signal £ by the operation of the print magnet PM of the multiplex printer and stepping the tape 11 ahead by the operation of the tape step magnet TM of the tape transmitter TTR1.

When segment 13 of the ring R1 is engaged by the brush DB1, relay SP operates and applies battery to the selection magnet SM3 of the printer to store the space signal therein. As brush DB1 engages segment 15 of the ring R1, relay PTR operates causing the space signal stored in the

monitor printer to be included in the printed record of the message, the tape step magnet TM operating at this time.

When segment 24 of the ring R1 is engaged by the brush DB1, relay AG operates and at the armatures 89 and 99 thereof removes battery from conductors 4 of cables 91 and 101 respectively. Relay AG also closes ground to the windings of indicators AT8 and AU8, ground having been removed from the windings of these indicators by the operation of their associated switch contacts 168 and 173 respectively which were opened as the indicators moved into their blank positions. Relay AG at armature 125 thereof causes relay G8 to operate thereby completing the ground circuit just described.

The digits 4 and 5 are stored in the first and second digit storage relays of Fig. 5 respectively, relays DT2 and DT4 of the first digit storage group and relay DU5 of the second digit storage group being operated. A circuit is closed from battery at armature 179 and break contact of relay DT1, armature 181 and make contact of relay DT2, armature 182 and break contact of relay DT3, armature 183 and make contact of relay DT4, break contact and armature 184 of relay DT5, conductor 3 of cable 91, make contact and armature 185 of relay P4, conductor 93, make contact and armature 166 of relay ALT, conductor 167, winding of indicator AT8, conductor 5 of cable 134, contact 132 of relay G8, conductor 5 of cable 124, armature 122 and make contact of relay AG to ground. As the brush DB1 engages segments 33, 35, 37 and 39 of the ring R1, relay P4 operates and transmits four impulses over the circuit just described thereby stepping the tens digit altitude indicator AT8 ahead to display the digit 4.

A circuit is closed from battery at armature 135 and break contact of relay DU1, armature 149 and break contact of relay DU2, armature 151 and break contact of relay DU3, armature 152 and break contact of relay DU4, make contact and armature 145 of relay DU5, conductor 1 of cable 101, make contact 140 and armature 158 of relay P1, conductor 103, make contact and armature 171 of relay ALT, conductor 172, winding of indicator AU8, conductor 6 of cable 134, contact 133 of relay G8, conductor 6 of cable 124, armature 123 and make contact of relay AG to ground. As brush DB1 passes over segment 26 of the ring R1 relay P1 operates and transmits the first actuation impulse to the indicator AU8 thereby stepping the indicator AU8 ahead to display the digit 1.

A circuit is closed from battery at armature 153 and break contact of relay DU1, armature 154 and break contact of relay DU2, armature 155 and break contact of relay DU3, armature 156 and make contact of relay DU5, armature 157 and break contact of relay DU4, conductor 3 of cable 101, contact 148 and armature 159 of relay P4, conductor 103 and thence by way of make contact and armature 171 of relay ALT and conductor 172 to the winding of the indicator unit AU8, conductor 6 of cable 134, contacts 133 of relay G8, conductor 6 of cable 124 to ground at armature 123 of relay AG. As the distributor brush DB1 engages segments 33, 35, 37 and 39 of the ring R1, relay P4 operates to transmit four additional actuation impulses to the indicator AU8, thereby stepping the indicator AU8 ahead to display the digit 5. The digits 4 and 5 are now displayed on the indicators AT8 and AU8 respectively and the information that flight 34 is sched-

uled to pass over the Camden fix at an altitude of 4500 feet at 1:35 is now posted on the indicators of level 8 of the flight progress board located at the Washington Airport and the seeker mechanism of Fig. 1 has been released. The flight information posted on the board has also been printed by the monitor printer of Fig. 1.

When the brush DB1 moves into engagement with segment 45 of the ring R1, ground is applied to conductor 161 causing relay REL to operate thereby releasing relays AG, GA8 and G8, the storage relay groups of Fig. 5, relay ALT, and relay TC. The brush DB1 of the distributor DR2 comes to rest in the position shown on the drawings with the ring R2 electrically connected to segment 1 of the ring R1 by the brush DB1.

Whereas in the example assumed, the posting message received over the line L included both time and altitude information signals, it will be understood that these signals may be sent in separate messages if desired; for example, if the information to be posted concerns time only the operator actuates the end-of-message key and the space bar of his keyset immediately following the operation of the time data keys. In a similar manner when altitude only is to be posted from a single message transmitted over the line L, the operator actuates the end-of-message key and the space bar immediately following the operation of the altitude data keys of the keyset. When such a message is received by the receiving apparatus of Fig. 1, the distributors DR1 and DR2 each make one revolution to select the desired indicators and actuate the same to their new settings.

Also, if desired, the operator may transmit a plurality of messages concerning different flights and different fixes over the line L followed by an end-of-message signal at the conclusion of this group of messages, in which case the seeker switch would maintain the associated perforated tape on which the messages are stored in operative relation with the indicator pulsing mechanism, the distributors DR1 and DR2 continuing their operations until the end-of-message signal is received on the seeker release relays RS1 to RS4 and the intelligence signals preceding the end-of-message signal is posted on the flight progress announcing board.

The teleprinters designated 1, 186 and 187 on Fig. 1 of the drawings may be of the type known in the art as 2B, or it may be a printer of somewhat lighter construction known in the telegraph art as the Western Union Type 102 printer with keyboard attachment for transmitting signals in permutation code, each group of signals comprising five code units permuted in accordance with the character to be transmitted, preceded by a start impulse and followed by a stop or rest impulse. A radio transmitter having an audio-frequency generator connected thereto is adapted to transmit radio signals comprising an audio frequency component introduced by the audio-frequency generator and controlled by telegraph signals received from the teleprinter. The audio-frequency generator associated with the teleprinter 186 may transmit any suitable frequency; as for example, a frequency of 500 cycles per second, the teleprinter 186, audio-frequency generator and associated radio transmitter being carried by an aircraft such, for example, as an airplane and adapted to transmit signals when in flight.

The teleprinter 187 may be identical with the teleprinter 186 but carried by a different air-

craft, the teleprinter 187 having an audio-frequency generator adapted to generate a frequency different from the frequency of the generator associated with teleprinter 186 as, for example, a frequency of 750 cycles per second, the teleprinter 187 and associated frequency generating and radio transmitting equipment being carried by another aircraft in flight. The radio receiver shown on Fig. 1 is tuned to the radio transmitting frequency of the radio transmitters and has associated therewith a plurality of audio-frequency filters each tuned to the frequency of the audio component of the signals received from the associated radio transmitter, the audio-frequency filter 1, for example, associated with teleprinter 186 being tuned to a frequency of 500 cycles per second, and the audio-frequency filter 2 associated with the teleprinter 187 tuned to a frequency of 750 cycles per second. The radio receiving equipment is connected to the distributors 188 and 189 by the lines L2 and L3 respectively, the distributors 188 and 189 being similar in all respects to the distributor 2 associated with the line L. Each distributor has associated therewith tape reperforating mechanism designated 191 and 192 having tapes 193 and 194 issuing therefrom and extending into tape transmitters TTR2 and TTR3, the tape transmitters TTR2 and TTR3 being identical with the tape transmitter TTR1. The contacts of distributor 188 are connected by way of conductors 1 to 5 of cable 195 extending to the end-of-message relays represented by the rectangle B1 which, when operated in response to an end-of-message signal, connects ground to conductor 196 thereby causing the operation of relay R1. The end-of-message relays lock over conductor 197 to the sixth pulse relay 20 of the associated distributor. The group of relays represented by the rectangles A1 and A2 are identical with the relays A and, similarly, the relays B1 and B2 are identical with the relays B. In a similar manner the contacts of distributor 189 are connected by way of conductors 1 to 5 of cable 199 to the end-of-message relays B2, these relays locking by way of conductor 201 to the sixth pulse relay of distributor 189.

When an end-of-message signal has been received by the group of relays B2, ground is applied to conductor 202 thereby causing the operation of relay R2, which locks by way of its armature 203 to ground on conductor 204 extending to the group of seeker release relays A2.

The group of relays A1 are operated over conductors 1 to 5 of cable 205, extending to the tongues of the tape transmitter TTR2. In a similar manner the windings of relays of group A2 are connected by way of conductors 1 to 5 of cable 206 extending to the tongues of the tape transmitter TTR3. When an end-of-message signal has passed through the tape transmitter TTR2, the relays of the group A1 operate to remove ground from conductor 206, armature 201 and make contact of relay R1, thereby releasing relay R1. In a similar manner, when the end-of-message signal is received by the group of relays A2, ground is removed from conductor 204 thereby causing relay R2 to release. The operation of relay R1 or R2, as the case may be, at its armature 21 causes the seeker switch stepping magnet SSM to operate and bring the wipers of the seeker switch into engagement with a set of terminals associated with the operated relays R1 or R2.

The operation of relay R1 at its armature 208 and make contact thereof applies battery to conductor 209, winding 1 of relay TC1, conductor

211, terminals 2 and 6 of level C of the seeker switch and wiper thereof, conductor 34, winding of the start magnet SM1, conductor 35, segment 1 of the ring R1, of the distributor DR2, brush DB1 to grounded ring R2 thereby operating relay TC1 and the start magnet SM1. Relay TC1 locks from battery, winding 2 of relay TC1, and contacts 212 thereof, conductor 38, break contact and armature 39 of relay REL to ground. The operation of the start magnet SM1 sets the distributor DR1 into operation to cause the message corresponding to the intelligence signals stored in the tape 193 to be posted on the flight progress board and printed by the multiplex printer.

When an end-of-message has been received by the relays B2, the operation of relay R2 at its armature 213 applies battery to conductor 214, winding 1 of relay TC2, conductor 215, terminals 1 and 5 of the level C and wiper thereof of the seeker switch, conductor 34, start magnet SM1, conductor 35 to ground on segment 1 of ring R1 of the distributor DR2, thus causing the operation of relay TC2 and distributor start magnet SM1. Relay TC2 locks by way of its winding 2 and contact 216 to ground on conductor 38.

In the event that the operator of teleprinter 1 at Camden, for example, should complete another message before the end-of-message signal is received by the seeker release relays RS1 to RS4, the auto-control contact 25 will be in closed position thereby applying ground to conductors 22, 24 and armature 21 and make contact thereof of relay L, and preventing the release of relay L by the operation of relay RS5 until the second message has passed through the tape transmitter. This feature enables the teleprinter operator to post two or more independent messages in succession as, for example, a message for the Camden fix followed by a message for the Baltimore fix, by preventing the release of the seeker mechanism until the successive messages have passed through the associated tape transmitter. When the last of these successive messages has passed through the associated tape transmitter, the decrease in the length of the loop of tape connecting the tape transmitter with the reperforator causes contact 25 of the auto-control mechanism to open and place the locking circuit for relay L under control of the end-of-message signal of the group of relay A. Relay R2, Fig. 1, it will be noted, locks to ground on conductor 204 extending to the group of relays A2 and to the contacts of auto-control AC2. In a similar manner the locking circuit for relay R1 is extended by way of conductor 217 to the relays of group A1 and the contacts of auto-control AC1.

Posting the board by keyset operation

The operation of the system in posting the flight progress announcing board by signals received from the local keyset will now be described. Assume, for example, that the local operator at the Washington Airport desires to post the arrival time of 1:20 for flight 15, the arrival time to be posted under that section of the board designated Washington Airport, Fix 3 of Fig. 9. It will also be assumed that flight 15 is the first to arrive at the Washington Airport and is posted at the bottom or 0 horizontal position of the board.

The operator operates the keys of his keyset in the following order: Horizontal position key 0, Data Tens and Units keys 2 and 0 respectively, and the range key TIME. Each of the operated keys of the keyset remain operated until released by the operator with the exception, as previously

stated, of the range keys which lock in the operated position until released by the key release magnet KR of the keyset. The range key TIME, therefore, is now locked under control of the key release magnet KR. The operation of key TIME at its contacts 218 applies ground by way of conductor 219 to the winding of relay K, Fig. 1, and thence to battery thereby causing relay K to operate and at its armature 21 interrupt the circuit to terminals 4 and 8 of the A level of the seeker switch and apply ground by way of the unoperated armatures 21 of relays L, R1 and R2 to the remaining terminal of level A thereby causing the seeker switch to operate by self-interruptions until either terminal 4 or 8 is engaged by the wiper of level A. The switch wipers are thus brought to rest on a terminal associated with the break contact of armature 21 of relay K, for example, the terminal 8. The relay K is held operated under control of the TIME range key of the keyset until the TIME key is restored by the key release magnet. A circuit is closed from battery at armature 220 and make contact of relay K, conductor 221, winding of relay KS, conductor 222, terminal 8 of the C level of the seeker switch and wiper thereof, conductor 223, terminal 8 of the B level of the seeker switch and associated wiper, conductor 35, segment 1 of Ring R1 of the distributor DR2, brush DB1 to ground on ring R2 thereby causing relay KS to operate and lock by way of its contacts 224 to ground.

The start magnet SM1 of the distributor DR is prevented from operating by the wiper of level B of the seeker switch engaging its terminal 8 and thus shortcircuiting the winding of the start magnet SM1. The operation of relay KS at its contacts 225 applies ground to conductor 2 of cable 226, break contact and armature 227 of relay SEQ, conductor 228, winding of start magnet SM2 of distributor DR2, the circuit continuing to battery, thereby causing the start magnet SM2 to withdraw the latch 81 and set the distributor DR2 into operation.

A circuit is completed from ground at the operated contacts of the horizontal position key 0, conductor 0 of cable 229, operated contact 231 of relay KS, conductor 0 of cable 232, armature 233 and break contact of relay GC1, conductor 0 of cable 234, armature 235 and break contact of relay SEQ—1, conductor 0 of cable 75, winding of gang relay GA0 to battery, thereby causing relay GA0 to operate and select the indicators of level 0 for operation. The operation of key TIME at its contacts 236 applies ground by way of operated contacts 237 of relay KS, conductor 6 of cable 88 and thence to the winding of range relay TIME, Fig. 6, thereby causing relay TIME to operate and close in part, impulse operating circuits to the time indicators TT0 and TU0 associated with the gang relay GA0 of level 0.

As the distributor brush engages terminals 2 and 23 of the ring R1 of the distributor DR2, ground is applied to conductor 82 causing relay ST to operate but perform no useful function at this time. As the brush DB1 passes over even numbered segments 4 to 22 of the ring R1, relay P1 operates thereby transmitting ten restoration impulses to the selected time indicators TT0 and TU0 over the following circuits: Battery, armature 89 and break contact of relay AG, conductor 4 of cable 91, make contact and armature 92 of relay P7, conductor 93, make contact and armature 94 of relay TIME, conductor 95, winding of indicator unit TT0, switch contacts 238, conductor 3 of cable 239, contacts 241 of relay GA0 to

ground. Battery, armature 99 and break contact of relay AG, conductor 4 of cable 101, make contact and armature 102 of relay P7, conductor 103, make contact and armature 104 of relay TIME, conductor 105, winding of indicator unit TU0 and switch contact 319 thereof, conductor 4 of cable 239, contacts 242 of relay GA0 to ground. The indicator units TT0 and TU0 are actuated by the restoration impulses received over the circuits just described from their previous settings to their blank positions at which time they come to rest with their associated switch contacts 238 and 319 in open position.

When the brush DB1 engages segment 5 of ring R1, ground is applied to conductor 1 of cable 109 extending to the winding of relays RS5 which do not operate at this time as no end-of-message signal is set up in the groups of relays A, A1 or A2. As the brush DB1 traverses segment 1 of ring R1, relay PTR operates and applies battery to conductor 2 of cable 109 extending to the print magnet PM of the multiplex printer to operate the same. As segment 13 of the ring R1 is engaged by the brush DB1, relay SP operates and applies battery to conductor 3 of cable 109 thereby operating the selection magnet SM3 of the multiplex printer. As the brush engages segment 15 of the ring R1, relay PTR operates thereby causing the print magnet to operate and the printer to function in response to the spacing signal stored therein by the operation of relay SM3.

The engagement of brush DB1 with segment 24 of the ring R1 operates relay AG which locks by way of the make contact and armature 116 thereof, conductor 1 of cable 47, break contact and armature 117 of relay REL to ground. Relay G0 operates from battery at the winding of relay G0, contacts 127 of relay GA0, conductor 126, armature 125 and make contact of relay AG to ground.

The operation of data tens key 2 applied battery to conductor 2 of cable 91, make contact 141 and armature 142 of relay P2, conductor 93, make contact and armature 94 of relay TIME, conductor 95, winding of indicator unit TT0, conductor 3 of cable 243, contact 244 of relay G0, conductor 3 of cable 124, armature 120 and make contact of relay AG to ground, thereby causing the time indicator TT0 to be stepped ahead to display the digit 2 as segments 28 and 30 of the ring R1 are traversed by the brush DB1 thereby causing the operation of relay P2.

The operation of the data units key 0 applied battery to conductors 1, 2 and 4 of cable 101, conductor 1 extending to contact 140 of relay P1, conductor 2 to contact 255 of relay P2 and conductor 4 to contact 256 of relay P1, the associated armatures of relays P1, P2 and P1 being connected together by conductor 103. The operation of relay P1 as the distributor brush engages segment 26 of the ring R1 applies a single battery impulse to conductor 103, thence by way of make contact and armature 104 of relay TIME, conductor 105, winding of indicator unit TU0, conductor 4 of cable 243, contacts 257 of relay G0, conductor 4 of cable 124, armature 121 and make contact of relay AG to ground, thereby operating the indicator unit TU0 and causing it to step ahead to display the digit 1. Two additional actuation impulses are applied to the indicator TU0 by the relay P2 as brush DB1 engages segments 28 and 30 of the ring R1, thereby causing the indicator to step ahead to display the digit 3. The engagement of the even numbered segments 32

to 44 of the ring R1 by the brush DB1 causes the pulsing relay P1 to apply seven additional actuation impulses to the indicator TU0 to step the same ahead to display the digit 0. 5 The time 20 is now displayed on the time indicators TT0 and TU0 of flight 15 located at the 0 level of the flight progress board. As the brush traversed the odd numbered segments 33 to 39 of the ring R1, relay P4 operated but performed no useful function at this time.

As brush DB1 moves into engagement with segment 45 of the ring R1, ground is applied to relay REL by way of conductor 161 causing relay REL to operate. As armature 117 of relay REL moves out of engagement with the break contact thereof, ground is removed from conductor 1 of cable 47 thereby releasing relay AG. As armature 117 of relay REL moves into engagement with the make contact thereof, ground is applied to conductor 258, armature 259 and break contact 261 of relay KS, winding of the key release magnet KR and thence to battery thereby causing the key release magnet to operate and release 25 the range key TIME.

The release of the TIME key removes ground from conductor 6 of cable 88, thereby releasing the relay TIME. The release of the TIME key also removes ground from conductor 219 extending to the winding of relay K, Fig. 1, thereby releasing relay K. The release of relay K at its armature 220 removes battery from conductor 221 extending to the winding of relay KS thus releasing relay KS. The release of relay KS

30 at its contacts 225 removes ground from conductor 2 of cable 226 thereby releasing the start magnet SM2 of the distributor DR2. Segment 46 of the ring R1 is of sufficient length to delay the engagement of the brush DB1 with the latch 35 81 until the start magnet SM2 has released. When this occurs the brush DB1 of the distributor DR2 comes to rest at the completion of its revolution with the brush in engagement with segment 1 of the ring R1. The release of relay KS at its contacts 231 caused relay GA0 to release. The release of relay GA0 at its contacts 127 interrupted the operating circuit for relay G0, causing relay G0 to release. As the brush DB1 passes off segment 45 of the ring R1, relay REL releases. The key release magnet KR released when contacts 261 of relay KS interrupted its operating circuit and the equipment is now restored to normal and in readiness to post another flight message.

55 Assume, for example, that the local keyset operator now desires to post an altitude of 2000 feet for flight 15 in the 0 level, the flight information appearing as the digits 20 on the altitude indicators of this level. The horizontal position 0 and data keys tens 2 and digits 0 now being in their operated position, it is merely necessary for the operator to depress the range key ALT. The operation of key ALT at contact 262 thereof applies ground to conductor 5 of cable 88 and thence to the winding of relay ALT causing relay ALT to operate. Relay ALT also applies ground to conductor 219 extending to relay K to cause relay K to operate and at the armature 220 and make contact thereof apply battery to conductor 221, winding of relay KS, conductor 222, contacts 4 and 8 of the switch bank C of the seeker switch and wiper thereof, conductor 223, contacts 4 and 8 of level P and wiper thereof, conductor 35, segment 1 of ring R1, brush DB1, ring R2 of the distributor DR2 to ground, thereby causing relay

KS to operate and lock by way of its contacts 224 to ground. Relay GA0 operates from ground at operated contacts of the horizontal position key 0.

The selected indicators AT0 and AU0 are restored to their blank positions and reset to display the digits 2 and 0 respectively, the restoration and actuation indicator impulses passing through armatures 166 and 171 of relay ALT as the distributor DR2 operates. The system operates in a manner similar to the operation of the system in posting the time on a selected group of indicators from signals received from the keyset and the circuits will, therefore, not be described in detail. It will be understood, however, that the distributor DR2 makes one revolution to control the operation of the selected indicators, the relay REL operating when the brush engages segment 45 of the ring RI thereof to cause the posting and control equipment to be restored to normal at the completion of the revolution of the distributor.

If the keyboard operator desires to change the setting of the flight identification indicators of the flight progress board the appropriate horizontal position key is operated and the data tens and units keys corresponding to the flight identification number to be posted are operated. The range key IDENT is now actuated thereby applying ground to the winding of relay K to operate the same and start the seeker into operation to select the keyset gang relay KS for operation. The IDENT key also applies ground to conductor 4 of cable 88 by way of operated contacts of relay KS, thereby causing the range relay IDENT, Fig. 6, to operate and select the flight identification indicators of the desired horizontal position for operation, the selected indicators being restored to their blank positions and reset to their new settings under control of the operated data tens and units keys respectively.

Changing the sequence of the information posted

Referring now to Fig. 9 of the drawings and more particularly to the Washington Airport section of the flight progress board, designated Fix 3, there is shown thereon groups of indicators associated with flights 15, 26, 51 and 34, posted on levels 0, 1, 2 and 3 respectively, the group of indicators on level 0 being associated with the flight first to arrive at the Washington Airport and the groups of indicators associated with levels 1, 2 and 3 being associated with flights posted in the order of their arrival at the airport; thus, flight 15 proceeding at an altitude of 2000 feet from Baltimore is scheduled to arrive first, followed by flights 26, 51 and 34 in the order stated.

Now let it be assumed that the local keyset operator at the Washington Airport receives word that flight 15 has been delayed one hour and, instead of arriving at the Washington Airport at 1:20, flight 15 will arrive at 2:20, the flying altitude between Baltimore and Washington for this flight of 2000 feet remaining unchanged. The order of arrival of the flights within the section Fix 3 will now be: flight 26, flight 51, flight 34 and flight 15, and the flight number 26 will be posted on the indicators of level 0, the flight number 51 on the indicators of level 1, the flight number 34 on the indicators of level 2, and the flight number 15 on the indicators of level 3. In a similar manner the time and altitude information for flight 26 will be posted on 75

the indicators of level 0, the corresponding information for flight 51 on level 1, for flight 34 on level 2 and for flight 15 on level 3.

The indicators of level 0 will be set to display the number 26 for the flight identification, 40 for time and 40 for altitude, the posting board now having the information previously posted on levels 1, 2 and 3 transferred to levels 0, 1 and 2 respectively and the information previously posted on level 0 transferred to level 3. This procedure of changing the order of arrival or the sequence of the flight information posted on the progress board is referred to herein as sequencing and is illustrative of one of the many rearrangement posting operations for which the present system is adapted.

The operator depresses horizontal position key 0, change position key 3, fix key 3, data tens key 0, data units key 0 and range key SEQ, 20 the key SEQ being operated after the other keys of the keyset have been operated. The operation of key SEQ applies ground to conductor 219 thereby causing relay K to operate. Key SEQ at the contact 263 thereof applies ground to conductor 264 extending to the winding of relay SEQ-1, the circuit being continued through the winding of relay SEQ-1 to battery, thereby causing relay SEQ-1 to operate. Conductor 264 is connected to conductor 3 of cable 226 extending 30 to the winding of relay SEQ, Fig. 7, and thence to battery thereby causing relay SEQ to operate in parallel with relay SEQ-1.

Relay KS operates over the following circuit: armature 220 and make contact of relay K, conductor 221, winding of relay KS, conductor 222, terminal 8 of level C and wiper thereof, conductor 223, terminal 8 of level B and wiper thereof of the seeker switch, conductor 35, segment 1 of ring RI of the distributor DR2, brush DB1 to ground on ring R2. Relay KS locks by way of its contact 224 to ground. When relay KS operates, ground at contacts 264 of key SEQ is applied by way of operated contacts of relay KS to conductors 4, 5 and 6 of cable 88 extending 45 to the windings of relays IDENT, ALT and TIME respectively thereby causing the range relays IDENT, ALT and TIME to operate. A circuit is closed from ground at contact 265 of change position key 3, contact 266 of horizontal position key 3, contact 267 of horizontal position keys 4, 5, 6, 7, 8 and 9 in series, conductor 268, contact 269 of relay KS, conductor 271, winding of relay TR to battery thereby operating relay TR. Conductor 271 also extends to the winding of transfer 55 relays TR1, TR2 and TR3, Fig. 7, thereby causing relays TR1, TR2 and TR3 to operate in parallel with relay TR.

Now let it be assumed that the sequence stepping switch STM, Fig. 7, has the wipers thereof resting on their terminals 8 at this time. The operation of horizontal position key 0 applies ground to conductor 0 of cable 229, contacts 231 of relay KS, conductor 0 of cable 232, armature 233 and break contact of relay GC1, conductor 60 0 of cable 234, armature 235 and make contact of relay SEQ-1, conductor 0 of cable 272, winding of relay G0 to battery, thereby causing relay G0 to operate. A circuit is closed from battery through the winding of the stepping magnet STM of the sequence switch, armature 273 and break contact thereof, conductor 274, winding of slow-release relay SR, armature 275, and break contact of relay SD, wiper C and terminal 8 of the sequence switch, conductor 4 of cable 276, contact and armature 277 of relay TR, contacts 278

of relay KS, conductor 5 of cable 279, contact 281 of change position key 5 which, it will be recalled, is unoperated, conductor 282, contact 283 of operated change position key 3 to ground thereby causing relay SR and the stepping magnet STM to operate.

The operation of the stepping magnet STM attracts its armature 273 thereby interrupting the circuit to the stepping magnet and relay SR causing the stepping magnet to release and the switch wipers to be advanced to their terminals 9. Relay SR, however, does not release at this time due to the slow-releasing characteristic of this relay. A circuit is now completed from battery to the winding of the stepping magnet STM and armature 273 and break contact thereof, conductor 274, winding of relay SR, armature 275 and break contact of relay SD, wiper C and terminal 9 of the sequence switch, conductor 284, armature 285 and break contact of relay SD, conductor 2 of cable 226, contact 225 of relay KS to ground thereby operating the stepping magnet STM and additionally energizing the winding of relay SR. The operation of the stepping magnet STM at its armature 273 interrupts the operating circuit thereto and causes the sequence switch wipers to be stepped ahead into engagement with their terminals 10. The stepping magnet STM now operates over a circuit including terminal 10 of level C, conductor 5 of cable 276, make contact and armature 286 of relay TR, contacts 287 of relay KS, conductor 4 of cable 279, contact 281 of change position key 4, conductor 282, operated contact 283 of change position key 3 to ground. The stepping magnet STM operates and advances the wipers of the switch to their terminals 11. With the switch wipers in engagement with their terminals 11, ground on conductor 288 is applied to wiper C, break contact and armature 275 of relay SD, winding of relay SR, conductor 274, break contact and armature 273, winding of stepping magnet STM to battery thereby causing the stepping magnet to operate and advance the switch wipers to their terminals 12.

Terminal 12 of level C of the sequence switch is connected by way of conductor 6 of cable 276, make contact and armature 288 of relay TR, contacts 289 of relay KS, conductor 3 of cable 279 to contacts 281 of change position key 3. With change position key 3 operated contacts 281 thereof are disengaged from one another thereby causing the circuit to terminal 12 of level C of the sequence switch to be open and the switch wipers to come to rest in engagement with their terminals 12. Relay SR now releases.

When relay SR operated in response to the first flow of current through the winding of the stepping magnet STM, ground at armature 291 of relay SR was applied by way of the make contacts thereof to the winding of relay C1 which operated and locked by way of its make contact and armature 292, conductor 2 of cable 226 and contacts 225 of relay KS to ground. When relay SR releases, battery at armature 293 and make contact of relay C1 is applied by way of armature 294 and break contact of relay SR to the winding of relay SD. The other end of the winding of relay SD is connected to conductor 2 of cable 226 extending to grounded contacts 225 of relay KS, thereby causing relay SD to operate and close a circuit 70 from ground at armature 291 and break contact of relay SR, make contact and armature 295 of relay SD, conductor 228, winding of start magnet SM2 and thence to battery, thereby causing the start magnet SM2 to operate and set the dis-

tributor DR2 into operation. A circuit is also closed from ground at armature 291 and break contact of relay SR, make contact and armature 296 of relay C1, conductor 297, wiper A and terminal 12 of the sequence switch, conductor 1 of cable 298, winding of relay A1, Fig. 6, to battery, thereby causing relay A1 to operate. Conductor 297 is also connected to wiper M of the sequence switch thereby applying ground by way of terminal 12 of level M, conductor 3 of cable 298, winding of relay M1, Fig. 6, and thence to battery, thereby causing relay M1 to operate.

As segment 2 of ring R1 of the distributor DR2 is traversed by the brush DB1, ground is applied by way of conductor 82 to the winding of relay ST, Fig. 7, thereby causing relay ST to operate and complete a circuit from ground at armature 299 and make contact of relay SEQ, conductor 303, make contact and armature 301 of relay ST, conductor 302, winding of stepping magnet STM to battery, thereby causing the stepping magnet to operate. As brush DB1 passes off segment 2 of the ring R1, relay ST releases, thereby removing ground from the winding of the stepping magnet STM and causing the stepping magnet to release and advance the wipers of the sequence switch mechanism to their terminals 13. As wiper A of the sequence switch passes off segment 12 of the associated bank, ground is removed from conductor 1 of cable 298 thus releasing relay A1. Relay M1, however, remains operated with the switch wipers on their terminals 13 for the reason that terminals 12 and 13 of the bank M are connected together.

The operation of relay ST applies ground at armature 299 and make contact of relay SEQ, conductor 303, make contact and armature 304 of relay ST, conductor 305, armature 306 and break contact of relay HG2, winding of relay HG1 to battery thereby causing relay HG1 to operate. A circuit is now closed from grounded conductor 305, armature 306 and break contact of relay HG2, armature 307 and make contact of relay HG1, winding of relay HG2, make contact and armature 299 of relay SEQ to ground on conductor 305 thereby preventing the operation of relay HG2. As the distributor brush DB1 moves off from segment 2 of the ring R1, relay ST releases thereby removing ground from conductor 305 and causing relay HG2 to operate in series with the winding of relay HG1. As armature 306 of relay HG2 moves away from its break contact, conductor 305 is disconnected from the winding of relay HG1 and connected by way of armature 306 and the make contacts thereof of relay HG2 to the winding of relay GAR. Ground at armature 308 and break contact of relay GAR is applied by way of make contact and armature 309 of relay HG1, conductor 11 of cable 272, extending to contacts 311 of gang relays G0 to G9, Fig. 3, and thence by way of operated contacts 311 of relay G0 to the winding of relay GA0 thus causing relay GA0 to operate.

When segment 4 of the ring R2 is engaged by the brush DB1, relay P1 operates and completes a circuit from battery at armature 89 and break contact of relay AG, conductor 4 of cable 91, make contact and armature 92 of relay P7, conductor 93, make contact and armature 312 of range relay IDENT, conductor 313, winding of storage indicator ITS1 of the group S1, conductor 1 of cable 314, contacts 315 of relay M1, conductor 1 of cable 124, contacts 316 of relay G0, conductor 1 of cable 243, contacts 317 of indicator unit IT0, conductor 1 of cable 239,

contacts 318 of relay GA8 to ground. Conductor 313, it will be noted, also extends to the winding of indicator unit IT0 whereby the indicator IT0 and the storage indicator ITS1 are operated in parallel over the circuit just described. When the brush DB1 leaves segment 4 of the ring R1, relay P1 releases thereby removing battery from the windings of the indicators IT0 and ITS1 causing the indicator IT0 to be stepped ahead to display the digit 2 and the storage indicator ITS1 to be stepped from its blank position to position 1. As the even-numbered segments 6 to 22 of the ring R1 are engaged by the brush DB1, relay P1 operates thereby applying nine additional impulses to the indicators IT0 and ITS1 to cause the indicator IT0 to be stepped ahead nine additional steps to its blank position and the storage indicator ITS1 to be stepped ahead to position 10, thereby displaying the digit 0 on the storage indicator ITS1.

Conductor 93 is also connected by way of contacts and armatures 94 and 166 of relays TIME and ALT to conductors 95 and 167 respectively, conductor 95 extending to the winding of indicators TT0 and storage indicator TTS1 and conductor 167 extending to the windings of indicators AT0 and ATS1. Indicator TT0 is stepped ahead by the first impulse received to position 3 and storage indicator TTS1 operating in parallel with indicator TT0 is stepped ahead to position 1 by the first impulse received from the relay P1. As the distributor brush DB1 engages even-numbered segments 6 to 18 of the ring R1, indicator TT0 receives seven additional impulses and is stepped ahead to display the digit 0 and the storage indicator TTS1 is also stepped ahead to position 8. The operation of relay P1 in response to the engagement of segment 20 of the ring R1 by the brush DB1 causes the indicator TT0 to be stepped ahead to its blank position and the storage indicator TTS1 to be stepped ahead to position 9. As indicator TT0 moves into its blank position, the associated switch contacts 238 are opened thereby removing ground from the windings of indicators TT0 and TTS1 and rendering these indicators unresponsive to the impulse received from relay P1 as the brush DB1 traverses segment 22 of the ring R1. The first digit flight identification number is now stored in the storage indicator ITS1 and the tens digit 2 of the time is stored in the storage indicator TTS1. In a similar manner the first digit of the altitude is stored in the storage indicator ATS1. While the brush DB1 was passing over even-numbered segments 4 to 22 of the ring R1, the second digits of the flight identification number, time and altitude were transferred from the indicators IU0, TOO and AU0 to the storage indicators IUS1, TUS1 and AUS1 respectively concurrently with the transfer of the first digit information to the storage indicators ITS1, TTS1 and AUS1.

As these circuits are similar, only the circuit for transferring the settings of the second digit 5 of the flight identification number to the storage indicator unit IUS1 will be described in detail. Battery at armature 99 and break contact of relay AG, conductor 4 of cable 101, make contact 256 and armature 102 of relay P1, conductor 103, make contact and armature 321 of relay IDENT, conductor 322, winding of storage indicator IUS1, conductor 2 of cable 314, contacts 323 of relay M1, conductor 2 of cable 124, contacts 324 of relay G0, conductor 2 of cable 243, switch contacts 325, conductor 2 of cable 75

238, contacts 326 of relay GA8 to ground. Battery on conductor 322 is also applied to the winding of indicator IU0 in parallel with the winding of storage indicator IUS1. When six impulses have been received from relay P1, the switch contacts 325 are opened by the movement of the indicator IU0 into its blank position thereby removing ground from the windings of indicators IU0 and IUS1 and causing indicator IUS1 to be set to position 6 and be unresponsive to additional impulses from relay P1 as even numbered segments 16 to 22 of the ring R1 are crossed by the brush DB1.

It will be understood that the settings of the zero level of indicators are now transferred to the corresponding storage indicators ITS1 to AUS1 of the storage group S1 during the passage of the brush DB1 over segments 4 to 22 of the ring DR2.

20 As terminal 23 of the ring R1 is engaged by brush DB1, relay ST operates and closes a circuit from ground at armature 299 and make contact of relay SEQ, conductor 303, make contact and armature 301 of relay ST, conductor 302 and thence to the winding of the sequence switch stepping magnet STM, thereby causing the stepping magnet to operate. Relay ST also applies ground on the armature 299 and make contact of relay SEQ, conductor 303, make contact and armature 304 of relay ST, conductor 305, armature 306 and make contact of relay HG2 to the winding of relay GAR thereby causing relay GAR to operate and lock by way of its armature 327 and make contact, conductor 303, make contact and armature 299 of relay SEQ to ground. As the distributor brush passes off segment 23 of the ring R1, relay ST releases thereby releasing the stepping magnet of the sequence switch and advancing the wipers thereof to their terminals 35 14. As wiper M moves off terminal 13 of the sequence switch bank M, ground is removed from conductor 3 of cable 298 thereby causing relay M1 to release. The operation of relay GAR at its armature 308 removes ground from conductor 11 of cable 212 thereby causing relay GA8 to release. With the brush A of the sequence switch in engagement with its terminal 14 ground is applied to conductor 2 of cable 298 extending to the winding of relay A2 thereby causing relay A2 to operate. In a similar manner the engagement of terminal 14 of the bank M by the sequence switch wiper applies ground to conductor 4 of cable 298 causing relay M2 to operate.

As segment 24 of the ring R1 is engaged by the brush DB1, ground is applied to the winding of relay AG but relay AG does not operate as battery is removed from the other end of the winding thereof by relay SEQ at its armature 115. The operation of relays P1, P2, P4 and P1 as brush DB1 crosses terminals 26 to 44 of the ring R1 is without effect at this time as ground is removed from the windings of the indicator units by relays GA8 and AG which are both in a released condition at this time.

65 As brush DB1 engages segment 45 of ring R1, ground is applied by way of conductor 161 to the winding of the release relay REL, thereby causing relay REL to operate. The operation of relay REL closed a circuit from grounded armature 328 and make contact of relay SEQ, conductor 329, armature 331 and make contact of relay REL, conductor 332 extending to the windings of relays GC and GCI in parallel, the circuits from these windings continuing to battery. Relays GC and GCI lock by way of armature 333

and make contact of relay GC, conductor 2 of cable 226, contact 225 of relay KS to ground. The operation of relay GC1 at its armature 233 removes ground from the winding of relay G0, causing relay G0 to release. As the brush passes off segment 45 of ring R1, relay REL releases. The start magnet SM2, it will be recalled, operates on a circuit from grounded armature 291 and break contact of relay SR, make contact and armature 295 of relay SD, conductor 288, winding of start magnet SM2 to battery. As relay SD remains operated, the latch 81 is held in an attracted position by the start magnet SM2 and the distributor brushes DB1 are not arrested at the completion of their revolution but continue to rotate continuously until the distributor has made five revolutions in the example assumed.

The circuit operations occurring during the second revolution of the distributor DR2 will now be described. When the brush DB1 engages segment 2 of the ring R1, the step relay ST operates thereby operating the stepping magnet STM and causing the switch wipers to be advanced to their terminals 15. As wiper A passes off terminal 14 of its bank, ground is removed from conductor 2 of cable 298 thereby releasing relay A2. Relay M2, however, does not release at this time as terminals 14 and 15 of level M of the sequence switch are connected together. The operation of relay GC at its armature 344 and make contact thereof applies ground to the wiper GA of the sequence switch and thence by way of its terminal 15, armature 340 and make contact of relay TR2, conductor 3 of cable 15, winding of gang relay GA3 to battery causing relay GA3 to operate. For the purpose of illustration without unnecessarily complicating the circuit drawings, the connections between the contacts of armatures 334 to 343 of relays TR2 and TR3 are indicated by the rectangle X, the manner of interconnecting the contacts to the cable conductors issuing from each rectangle being identical with the circuit arrangement within the rectangle X for the relay TR1. Like numerals of reference have been applied to corresponding armatures of relays TR1, TR2 and TR3 to render the circuits to these relays to be more easily traced. It will be noted that the conductors 1 to 1 of cable 75 extend to the windings of relays GA1 to GA7 respectively and conductors 1 to 7 of cable 272 to the windings of relays G1 to G7 respectively. Also, conductors 1 to 1 of cable 272 extend to contacts 127 of relays GA1 to GA7 and conductors 11 to 17 of cable 345 to contacts 366 of relays G1 to G7. Furthermore, cable 124 has branches extending therefrom to the contacts of relays G1 to G7, the G and GA relays and associated group of indicators for each of the levels 1 to 7 being wired in an identical manner with the relays and indicators of levels 0, 8 and 9.

The operation of relay GC at armature 344 and make contact thereof applies ground by way of wiper G and terminal 15 of the seeker switch, armature 340 and make contact of relay TR3, conductor 3 of cable 272 and thence to the winding of relay G3 causing relay G3 to operate. With relays M2 and G3 operated, the storage indicators ITS2 to AUS2 of the group S2 are connected in parallel with the indicators IT3 to AU3 of level 3, the circuit being continued by way of the switch contacts of the indicators of level 3 to ground at operated contacts of relay GA3. As brush DB1 passes over the even-numbered segments 4 to 22 of ring R1, relay PI applies ten battery impulses to the windings of these indi-

cators thereby restoring the indicators of level 3 to their blank positions and causing the information posted by these indicators to be stored in the storage indicators S2. As each of the indicators IT3 to AU3 move into their blank positions, the associated switch contacts are opened thereby removing ground from their windings and the windings of the associated indicators ITS2 to AUS2 whereby these indicators are prevented from operating on additional impulses received from relay PI during the travel of the distributor brush over the remaining even-numbered segments 4 to 22 of the ring R1.

As terminal 23 of the ring R1 is engaged by the brush DB1, relay ST operates thereby causing the wipers of the sequence switch to be stepped ahead to their terminals 16. As wiper GA passes off terminal 15 of the associated switch bank, relay GA3 releases. Relay G3, however, does not release with the wipers on their terminals 16 for the reason that terminals 15 and 16 of the level G are connected together.

As wiper M passes off segment 15 of its associated bank, ground is removed from conductor 4 of cable 298 thereby releasing relay M2. The engagement of terminal 16 of level M of the sequence switch by its brush applies ground to conductor 3 of cable 298, thereby causing relay M1 to operate. When wiper A of the sequence switch comes into contact with terminal 16, ground is applied by way of conductor 1 of cable 298 to the winding of relay A1 which operates. As the brush DB1 passes over segments 26 to 44 of the ring R1, relays P1, P2 and P7 operate and transmit impulses to the storage indicators S1 in parallel with the indicators of level 3 which, it will be recalled, have just been restored to their blank positions, whereby the flight information stored in the storage indicators S1 is transferred to the indicators of level 3. As each of the storage indicators S1 is moved into its blank position, the corresponding switch contact is opened thereby preventing further actuation of the storage indicator and associated pulsing indicator of level 45 by removing the ground from the windings of these indicators and causing them to be unresponsive to additional impulses received from the pulsing relays during the passage of the brush DB1 over the group of segments 26 to 44 of ring R1. The circuit of one of these pairs of indicators, for example, the second digit flight identification indicators IU3 and IUS1, will now be described. The indicator IUS1 has been set to position 6, it will be recalled, corresponding to the digit 5 stored therein and the associated switch contacts 346 thereof are closed. When relay PI operates in response to the engagement of segment 26 of the ring R1 by the brush DB1, battery is applied by way of armature 158 of relay PI, conductor 103, make contact and armature 321 of relay IDENT, winding of storage indicator IUS1, switch contact 346 thereof, conductor 2 of cable 347, contacts 348 of relay A1 to ground. The winding of indicator IU3 has one end thereof connected to one end of the winding of indicator IUS1 by the conductor 322, the other end of these windings being connected by conductor 2 of cable 344, contacts 323 of relay M1, conductor 2 of cable 124, contacts 324 of relay G3, conductor 3 of cable 243 of level 3 and thence to the winding of indicator IU3. When relay PI releases indicator IUS1 is stepped ahead to its position 7 and indicator IU3 to its position 1. As three additional impulses are received over conductor 103, the indicator IUS1 is stepped

ahead to its position 6 and indicator IUS1 to its position 4. As the fifth impulse is received over conductor 103 the storage indicator IUS1 is moved into its blank position thereby opening the switch contacts 346 and the indicator IUS1 is moved into position 5. The remaining five impulses received on conductor 103 are ineffective to move the indicator IUS1 beyond its position 5 or the indicator IUS1 for the reason that ground is removed from the windings of these indicators by the switch contact 346 of indicator IUS1. The digit 5 corresponding to the second digit of the flight identification number previously posted in level 0 has been transferred to level 3. In a similar manner the information stored in the indicators ITS1, TTS1, TUS1, ATS1 and AUS1 is transferred to the corresponding indicators of level 3 while the brush DB1 is passing over the group of segments 26 to 44 of the ring R1. The entire message posted by the indicators of level 0 has now been transferred to the indicators of level 3 and the information previously posted on level 3 has been transferred to the storage indicators S2 and the indicators of S1 have been restored to their blank settings. As distributor brush DB1 crosses segment 45 of the ring R1, relay REL operates.

The engagement of segment 2 of the ring R1 by the brush DB1 during the succeeding revolution of the distributor causes the operation of relay ST and the switch wipers to be stepped ahead to their terminals 17. As wiper G moves off segment 16 of its switch bank, ground is removed from conductor 3 of cable 272 thereby causing relay G3 to release. As wiper A of the sequence switch moves off terminal 16 of its associated bank ground is removed from conductor 1 of cable 298 thereby releasing relay A1. As wiper G engages terminal 17 of its switch bank ground is applied by way of armature 341 and make contact of relay TR3, conductor 2 of cable 272 to the winding of relay G2, causing relay G2 to operate. As wiper GA of the sequence switch engages its terminal 17, ground is applied to armature 341 and make contact of relay TR2 by way of conductor 2 of cable 75 and thence to the winding of relay GA2 causing relay GA2 to operate. With the wiper M in engagement with its terminal 17 relay M1 remains operated for the reason that terminals 16 and 17 of the switch level M are connected together. With relays G2, GA2 and M1 operated the information stored in the indicators of level 2 are transferred to the storage indicators S1 during the passage of the brush DB1 over the even-numbered terminals 4 to 22, the indicators of level 2 being set to their blank positions.

As terminal 23 of the ring R1 is engaged by the brush DB1, relay ST operates thereby causing the switch wipers to be advanced to their terminals 18. As the wiper GA moves away from terminal 17 of its associated switch bank, ground is removed from conductor 2 of cable 75 causing relay GA2 to release. As wiper M moves off terminal 17 of its bank, ground is removed from conductor 3 of cable 298 causing relay M1 to release. When wiper M moves into engagement with its terminal 18, ground is applied to conductor 4 of cable 298 thereby causing relay M2 to operate. As brush A engages terminal 18 of its associated bank, ground is applied to conductor 2 of cable 298, thereby operating relay A2. Relay G2 remains operated with the switch in position 18 for the reason that terminals 17 and 18 of level G are connected together.

As the brush DB1 crosses the group of segments 26 to 44 the information stored in the group of storage devices S2 is transferred to the indicators of level 2. At the completion of this third revolution of the distributor DR2, the information previously posted on level 3 has been transferred to the indicators of level 2 and the storage indicators S2 have now been restored to their blank position. As segment 45 of the ring R1 is traversed by the brush DB1, relay REL operates. The distributor DR2 now begins a fourth revolution.

As segment 2 of the ring R1 is engaged by brush DB1, relay ST operates thereby causing the wipers of the sequence switch to be advanced to their terminals 19.

As wiper G passes off terminal 18 of its associated switch bank, ground is removed from conductor 2 of cable 272 thereby releasing relay G2. As wiper A passes off terminal 18 of its switch bank, ground is removed from conductor 2 of cable 298 thereby releasing relay A2. Relay M2, however, does not release for the reason that terminals 18 and 19 of switch bank M are connected together. As the wiper G engages terminal 19 of its associated bank, ground is connected by way of armature 342 and make contact of relay TR3, conductor 1 of cable 272, winding of relay G1 to battery, thereby causing relay G1 to operate. Ground at wiper GA is applied by way of terminal 19 of the associated switch bank, armature 342 and make contact of relay TR2, conductor 1 of cable 75 and thence to the winding of relay GA1 causing relay GA1 to operate.

With relays GA, GA1 and M2 operated, the flight message posted on the indicators of level 1 is transferred to the storage indicators S2 during the passage of the brush DB1 over the even-numbered segments 4 to 22 of the ring R1. As segment 23 of the ring R1 is traversed by the brush DB1, relay ST operates causing the switch wipers to be advanced to their terminals 20. As wiper GA moves out of engagement with its associated terminal 19, ground is removed from conductor 1 of cable 75 thereby causing relay GA1 to release. Relay G1, however, does not release for the reason that terminals 19 and 20 of the level G are connected together. As wiper A is brought into engagement with its terminal 20, ground is applied to conductor 1 of cable 298, thereby causing relay A1 to operate. When wiper M engages its terminal 20, ground is applied by way of conductor 3 of cable 298 to the winding of relay M1, thereby causing relay M1 to operate. With relays G1, A1 and M1 operated, the information stored in the storage indicators S1 is transferred to the indicators of the level 1. At the completion of this fourth revolution of the distributor, the information previously posted by the indicators of level 2 has been transferred to level 1 and the storage devices S1 are restored to their blank position. As segment 45 of the ring R1 is crossed by the brush DB1, relay REL operates. The distributor now makes a fifth revolution.

As segment 2 of the ring R1 is traversed by the brush DB1, relay ST operates and causes the wipers of the sequence switch to be advanced to their terminals 21. As wiper G moved off its terminal 20 ground is removed from conductor 1 of cable 272 thereby releasing relay G1. As brush A passes off terminal 20 of its switch bank ground is removed from conductor 1 of cable 298 thereby causing relay A1 to release. Ground at wiper G is applied by way of terminal 21 of the associated switch bank, armature 343 and make con-

tact of relay TR3, conductor 0 of cable 272 and thence to the winding of relay G0, causing relay G0 to operate. Ground at wiper GA and terminal 21 of the associated switch bank is applied by way of armature 343 and make contact of relay TR2, conductor 0 of cable 75, to the winding of relay GA0 causing relay GA0 to operate. Relay M1 does not release with the wipers on their terminals 21 for the reason that terminals 20 and 21 of level M are connected together.

With relays G0, GA0 and M1 operated, the indicators of level 0 are connected to the storage indicators S1 but, as will be recalled, the indicators of level 0 were restored to their blank settings during the first revolution of the distributor DR2 and ground at the operated contacts of relay GA0 is, therefore, disconnected from its windings of the indicators of level 0 and the storage indicators S1 at the operated switch contacts of the indicators of level 0, which are in open position at this time. For this reason, the passage of brush DB1 over the even-numbered segments 4 to 22 of the ring R1 during this revolution of the distributor merely operates relay P1 without changing the settings of the indicators of level 0 or the storage indicators S1. As brush DB1 engages segment 23 of the ring R1, relay ST operates and causes the wipers of the sequence switch to be advanced to their terminals 22. As wiper GA moves out of engagement with its terminal 21, ground is removed from conductor 0 of cable 75 thereby releasing relay GA0. As brush M moves off terminal 21 of the sequence switch bank M, ground is removed from conductor 3 of cable 298 thereby releasing relay M1. The engagement of terminal 22 by the brush A applies ground to conductor 2 of cable 298 thereby operating relay A2. As brush M moves into engagement with terminal 22 of its associated bank, ground is applied to conductor 4 of cable 298 thereby operating relay M2.

When brush CP engages terminal 22 of its associated bank, a circuit is closed from ground at operated contacts of horizontal position key 0, conductor 0 of cable 299, contacts 231 of relay KS, conductor 0 of cable 232, armature 233 and make contact of relay GC1, conductor 0 of cable 348, make contact and armature 343 of relay TR1, terminal 22 and wiper CP of the sequence switch, winding of relay EQ, and thence to battery, thereby causing relay EQ to operate. Relay G0 remains operated with the wiper G resting on its terminal 22 for the reason that terminals 21 and 22 of the switch level G are connected together.

With relays G0, A2 and M2 operated, the flight information stored in the storage indicators S2 is transferred to the flight indicators of level 0 as the brush DB passes over segments 26 to 44 of the ring R1, and the storage indicators S2 are thereby restored to their blank positions. The flight information previously posted on level 0 is now posted on level 3 and the information posted on levels 3, 2 and 1 is now posted on levels 2, 1 and 0 respectively.

As the distributor brush DB1 moves into engagement with segment 45 of ring R1, ground is applied to conductor 161 thereby causing the release relay REL to operate and at its armature 117 and make contact thereof apply ground to conductor 258, make contact and armature 349 of relay EQ, conductor 1 of cable 226, contacts 261 of relay KS, winding of key release magnet KR and thence to battery thereby causing the key release magnet to operate and release the range key SEQ. The release of the key SEQ removes

ground from conductor 219 thereby releasing the seeker relay K, Fig. 1. As the armature 220 of relay K moves to its release position battery is removed from conductor 221 thereby releasing the keyset relay KS. The release of key SEQ also removes ground from conductor 264 and conductor 3 of cable 226 thereby releasing relays SEQ and SEQ-1. The release of the range key also removes ground from conductors 4, 5 and 6 of cable 88 thereby releasing the range relays IDENT, ALT and TIME. The release of relay KS at its contacts 269 removes ground from conductor 271 thereby releasing relays TR, TR1, TR2 and TR3. The release of relay KS at its contacts 225 removes

ground from conductor 2 of cable 226 thereby releasing relays CI and GC. The release of relay CI at its armature 293 removes battery from relay SD causing relay SD to release. The release of relay SD removes ground from the winding of the start magnet SM2 causing the start magnet SM2 to release and arrest the distributor brush DB1 at the completion of the fifth revolution thereof.

The release of relay CI at its armature 296 removes ground from the wipers A and M of the sequence switch thereby releasing relays A2 and M2. The release of relay GC at its armature 344 removes ground from the wiper G, thereby releasing relay G0. The release of relay KS at its contacts 231 removes ground from the winding of relay EQ, causing relay EQ to release. The release of relay SEQ at its armature 299 removes ground from conductor 303, thereby releasing relays HG1, HG2 and GAR. As the brush DB1 passed off segment 45 of the ring R1, relay REL released thereby removing ground from conductor 1 of cable 226 and causing the key release magnet KR to be released. The distributor now comes to rest with the brush DB1 in engagement with segment 1 of the ring R1.

In the foregoing example it will be noted that the information stored on the indicators of level 0 was transferred to the indicators of level 3 and the information stored on levels 3, 2 and 1 was moved downward to levels 2, 1 and 0 respectively. The system disclosed herein possesses extreme flexibility and is adapted to shift any message posted on the flight progress board either upward or downward as required by the conditions of service for which the system is adapted and provides means for automatically shifting the information posted by other horizontal position indicators either upward or downward in accordance with the direction of movement of the information first shifted. This will best be understood by consideration of a specific example. Assume, by way of example, that the information posted on the indicators of horizontal position 3 is to be transferred to the indicators of horizontal position 0 and the information posted by the horizontal position of level indicators 2, 1 and 0 is to be shifted upward to the indicators of levels 3, 2 and 1 respectively.

The operator depresses the following keys of his keyset, fix key 3, horizontal position key 3, change position key 0, data tens key 0, and data units key 0 followed by the range key SEQ. With horizontal position key 3 and change position key 0 operated, ground is not applied to conductor 268 for the reason that the circuit from conductor 268 to the grounded contact of the operated change position key 0 is interrupted at contacts 267 of the operated horizontal position key 3 and therefore as relay KS closes its contacts 269, relays TR, Fig. 2, TR1, TR2 and TR3, Fig. 7, will remain unoperated.

The operation of change position key 0 at its contact 351 interrupts the circuit to conductor 0 of cable 279 and at its contact 352 applies ground by way of conductor 282, break contacts 281 of change position keys 1 to 9, conductors 1 to 9 of cable 279 and thence by way of operated contacts of relay KS, armatures and break contacts of relay TR to correspondingly designated conductors of cable 276 extending to even-numbered terminals 2 to 18 of switch bank C of the sequence switch. As ground is now connected to all of these conductors except conductor 0, the sequence switch is operated by self-interruptions until the wipers thereof are brought into engagement with their terminals 25. As wiper C engages terminal 25 of its switch bank, ground is removed from the operating circuit of stepping magnet STM by the operated contact 351 of change position key 0, thereby causing the switch wipers to come to rest on their terminals 25 and relay SR which, it will be recalled, was held operated while the switch was operating on self-interruptions now releases. The operation of relay SR, caused relay CI to operate and lock to ground on conductor 2 of cable 266. The release of relay SR at armature 291 and break contact thereof applies ground by way of make contact and armature 295 of relay SD to the winding of the start magnet SM2 thereby setting the distributor DR2 into operation.

As brush DB1 engages segment 2 of the ring R1 during the first revolution of the distributor, relay ST operates thereby stepping the sequence switch wipers ahead to their terminals 1. When wiper M engages segment 1 of its associated switch bank, ground is applied to conductor 3 of cable 298 thereby operating relay M1. Ground at operated contacts of horizontal position key 3 is applied by way of conductor 3 of cable 229, operated contacts of relay KS, conductor 3 of cable 232, armature 353 and break contact of relay GC1, conductor 3 of cable 234, armature 354 and make contact of relay SEQ-1, conductor 3 of cable 272, winding of relay G3, to battery, thereby causing relay G3 to operate. The operation of relay SEQ at its armature 299 applied ground to conductor 303 thereby causing relay HG2 to operate in series with relay HG1 after the step relay ST has released. Ground at armature 308 and break contact of relay GAR is applied by way of make contact and armature 309 of relay HG1, conductor 11 of cable 272, contact 311 of relay G3 to the winding of relay GA3 and thence to battery, thereby causing relay GA3 to operate. With relays G3, GA3 and M1 operated, the information stored in the indicators of level 3 is transferred to the storage indicators S1 during the passage of the brush DB1 over the even-numbered segments 4 to 22 of the ring R1. As segment 23 of the ring R1 is traversed by the brush DB1, relay ST operates causing the switch wipers to be advanced to their terminals 2. As wiper M passes off its terminal 1, ground is removed from conductor 3 of cable 298 causing relay M1 to release. The operation of relay ST at its armature 304 causes relay GAR to operate and remove ground from conductor 11 of cable 272 thereby releasing relay GA3.

As the brush DB1 crosses segments 26 to 44 the pulsing relays operate but perform no useful function at this time for the reason that the switch contacts of the storage indicators S2 are open at this time and the indicators, therefore, remain on their blank settings. Relays A2 and M2 operate as wipers A and M move into engagement with their segments 2, thereby closing the

circuit in part from the storage indicators S2 to the indicators of level 3.

When the distributor brush engages terminal 2 of the ring R1 during the second revolution of the distributor, relay ST operates and causes the switch wipers to be advanced to their terminals 3 thereby releasing relay A2 and holding relay M2 operated. Relay GC, it will be noted, operated during the passage of brush DB1 over segment 45 of the distributor from ground at contact and armature 331 of relay REL and locked by way of its armature 333 to ground on conductor 2 of cable 226. With relay GC operated ground is applied to the wipers GA and G, the circuit from wiper GA continuing by way of armature 334 and break contact of relay TR2, conductor 0 of cable 75 to the winding of GA0 causing relay GA0 to operate and the circuit from wiper G continuing by way of terminal 3, armature 334 and break contact of relay TR3, conductor 0 of cable 212 to the winding of relay G0 causing relay G0 to operate. With relays M2, G0 and GA0 operated, the information posted by the indicators of level 0 are transferred to the storage indicators S2 as the brush DB1 passes over even-numbered segments 4 to 22 of the ring R1.

As segment 23 is engaged by the brush DB1 the sequence switch wipers are moved to their terminals 4 thereby releasing relay M2 and operating relay M1. Relay A1 operates as brush A moves into engagement with its contact 4. Relay G0 is held operated by ground on terminal 4 of level G of the sequence switch. As wiper GA moves off terminal 3, relay GA0 releases. With relays G0, A1 and M1 operated, the information stored in the storage indicators S1 is transferred to the indicators of level 0 as brush DB1 passes over segments 26 to 44 of the ring R1. The message previously posted on level 3 has now been transferred to the indicators of level 0. As segment 45 is traversed by the brush DB1 relay REL operates.

As the brush DB1 engages segment 2 of the ring R1 during the third revolution of the distributor DR2, the sequence switch wipers are stepped ahead to their terminals 5. Relay M1 does not release as terminals 4 and 5 of level M are connected together. As wiper A moves from terminals 4 to 5 of its switch bank, relay A1 releases.

As wiper G engages terminal 5 of its switch bank, ground is applied to armature 335 and break contact of relay TR3, conductor 1 of cable 272 and thence to the winding of relay G1, causing relay G1 to operate. As wiper GA engages its terminal 5, ground is applied by way of armature 335 and break contact of relay TR2, conductor 1 of cable 75, and thence to the winding of relay GA1 causing relay GA1 to operate. With relays G1, GA1 and M1 operated, the message posted by the indicators of level 1 are transferred to the storage indicator S1 as the distributor brush passes over segments 4 to 22 of the ring R1.

As segment 23 of the ring R1 is engaged by the brush DB1, the switch wipers are advanced to their terminals 6. As wiper GA moves off its terminal 5, ground is removed from conductor 1 of cable 75 thereby releasing relay GA1. Relay G1, however, does not release as terminals 5 and 6 of the level G of the switch are connected together. As wiper M moves from terminal 5 to terminal 6 of its associated switch bank, relay M1 releases and relay M2 operates. As wiper A moves into engagement with its terminal 6, ground

is applied by way of conductor 2 of cable 298 to the winding of relay A2, thereby causing relay A2 to operate. With relays M2, A2 and G1 operated, the information stored in the storage indicators S2 is transferred to the indicators of level 1 as the distributor brush passes over segments 26 to 44 of the distributor DR2. As the brush crosses segment 45 of the distributor DR2, relay REL operates. The information previously stored on the indicators of level 0 has now been transferred to the indicators of level 1.

As segment 2 of the distributor DR2 is engaged by the brush DB1, the wipers of the sequence switch are advanced to their terminals 7. As wiper G passes from terminal 6 to terminal 7, ground is removed from conductor 1 of cable 272 and relay G1 releases. The engagement of terminal 7 by the wiper G applies ground by way of armature 336 and break contact of relay TR3, conductor 2 of cable 272 to the winding of relay G2, causing relay G2 to operate. As wiper GA moves into engagement with its terminal 7, ground is applied by way of armature 336 and break contact of relay TR2, conductor 2 of cable 15 to the winding of relay GA2 causing relay GA2 to operate. As wiper A moves away from its terminal 6, ground is removed from conductor 2 of cable 298 thereby releasing relay A2.

Relay M2 is held operated by ground on conductor 4 of cable 298 applied by way of terminal 7 of the switch bank M. With relays G2, GA2 and M2 operated, the information posted on level 2 of the flight progress board is transferred to the storage indicators of the group S2 as segments 4 to 22 of the distributor DR2 are traversed by the brush DB1.

As segment 23 is traversed by the brush DB1, the sequence switch wipers are advanced to their terminals 8. As wiper GA moves off its terminal 7, relay GA2 releases. Relay G2, however, remains operated for the reason that terminals 7 and 8 of the switch level G are connected together. As wiper A moves into engagement with its terminal 8, ground is applied by way of conductor 1 of cable 298 to the winding of relay A1, causing relay A1 to operate. As wiper M moves from its terminal 7 to terminal 8, ground is applied by way of conductor 3 of cable 298 to the winding of relay M1, causing relay M1 to operate and relay M2 to release. With relays A1, M1 and G2 operated, the information stored in the storage indicators S1 is transferred to the indicators of level 2 as the brush DB1 passes over segments 26 to 44 of the distributor DR2. The information previously posted on level 1 of the flight progress board has now been transferred to the indicators of level 2. As segment 45 of the distributor DR2 is crossed by the brush DB1, relay REL operates.

As brush DB1 passes over segment 2 of the ring R1, the wipers of the sequence switch are stepped ahead to their terminals 9. As wiper G moves off its terminal 8, relay G2 releases and as wiper G moves into engagement with its terminal 9, ground is applied by way of armature 337 and break contact of relay TR3, conductor 3 of cable 272 to the winding of relay G3 causing relay G3 to operate. As wiper GA engages its terminal 9 ground is applied by way of armature 337 and break contact of relay TR2, conductor 3 of cable 15 to the winding of relay GA3, causing relay GA3 to operate. As wiper A moves off its terminal 8, relay A1 releases. With wiper M in engagement with its terminal 9, relay M1 remains operated.

With relays G3, GA3 and M1 operated the indicators of level 3 are connected to the storage indicators S1 but, as will be recalled, the indicators of level 3 are now resting at their blank settings with their associated switch contacts in open position, and for this reason these indicators and the storage indicators S1 remain on their blank settings while segments 4 to 22 of the distributor DR2 are being traversed by the brush DB1 during this fifth revolution of the distributor. As the brush crosses segment 23 of the distributor the wipers of the sequence switch are stepped ahead to their terminals 10. As wiper GA moves out of engagement with its contact 9, ground is removed from the winding of relay GA3 thereby causing relay GA3 to release. G3 remains operated, however, as terminals 9 and 10 of level G are connected together. As wiper A engages its terminal 10, ground is applied by way of conductor 2 of cable 298 to the winding of relay A2 causing relay A2 to operate. As wiper M passes from terminal 9 to terminal 10 of its switch bank, relay M1 releases and relay M2 operates. As wiper CP moves into engagement with its terminal 10, ground at operated contacts of horizontal position key 3 is applied by way of conductor 3 of cable 229, operated contacts of relay KS, conductor 3 of cable 232, armature 353 and make contact of relay GC1, conductor 3 of cable 348, break contact and armature 337 of relay TR1, terminal 10 and wiper CP of the sequence switch, winding of relay EQ, and thence to battery thereby causing relay EQ to operate. With relays M2, A2 and G3 operated the information stored in the storage indicators S2 is transferred to the indicators of level 3 during the passage of the brush DB1 over terminals 26 to 44 of the distributor DR2. The information previously posted on level 2 of the flight progress board has now been transferred to the indicators of level 3. As segment 45 of the ring R1 is engaged by the brush DB1, relay REL operates and applies ground by way of its armature 117 and make contact, conductor 258, make contact and armature 349 of relay EQ, conductor 1 of cable 226, contacts 261 of relay KS to the winding of the key release magnet KR, thereby operating the key release magnet and releasing the range key SEQ.

The release of the key SEQ causes the seeker relay K and the relays SEQ, SEQ-1 and the range relays IDENT, TIME and ALT to release. The release of relay K at its armature 220 removes battery from the winding of relay KS, thereby releasing the keyset relay which, at its contact 225, removes ground from the windings of relays CI and GC causing relays CI and GC to release. The release of relay CI causes relay SD to release and at armature 295 thereof remove ground from the winding of the start magnet SM2, thereby causing the distributor DR2 to come to rest with the brush DB1 in engagement with segment 1 of the ring R1. With relays CI and GC released, ground is removed from the wipers A, M, GA and G of the sequence switch thereby releasing relays A2, M2 and G3. The release of relay SEQ at armature 299 thereof removes ground from the windings of relays HG1, HG2 and GAR causing these relays to release. The release of relay KS interrupts the circuit from grounded key 3 of the horizontal position keys extending to the winding of relay EQ thereby causing relay EQ to release. As brush DB1 passes off terminal 45 of the ring R1, relay REL releases. The information previously posted

on level 0 has now been transferred to level 0 and the information previously posted on levels 0, 1 and 2 has been transferred to levels 1, 2 and 3 respectively, the distributor DR2 making five revolutions during this sequence operation. It will be noted that the sequence switch wipers remain on their terminal 10 and the storage indicators SI and S2 are restored to their blank position.

Wipe-out of information posted

The manner in which the indicators of any desired level may be restored to their blank settings thereby eradicating the information posted by these indicators will now be described. The operation of this feature will best be understood by consideration of a specific example. Referring now to Fig. 9 of the drawings, and more specifically, to the indicators of level 0 of the flight progress board, let it be assumed that flight 15 posted at this level has terminated, the aircraft identified by number 15 having landed at the Washington Airport. To wipe-out the information posted by the indicators of level 0, for example, it is merely necessary for the operator to depress the keys, horizontal position 0 and the range key W0 of his keyset. The operation of key W0 at its contacts 355 applies ground to conductor 219 thereby operating relay K and causing the seeker switch to come to rest on a keyset position and relay KS to operate and at its contact 225 apply ground by way of conductor 2 of cable 226, break contact and armature 227 of relay SEQ, conductor 228, extending to the winding of the start magnet SM2 of the distributor DR2, thereby causing the start magnet to operate and set the distributor into operation. The operation of the horizontal position key 0 applies ground by way of conductor 0 of cable 229, contacts 231 of relay KS, conductor 0 of cable 232, armature 233 and break contact of relay GC1, conductor 0 of cable 234, armature 235 and break contact of relay SEQ-1, conductor 0 of cable 15 and thence to the winding of relay GA0. The operation of key W0 at its contacts 356 applies ground by way of operated contacts of relay KS, and conductors 4, 5 and 6 of cable 88 to the windings of the range relays IDENT, TIME and ALT thereby operating these range relays and thus closing in part impulse restoration circuits to the windings of the indicators ITO, IU0, TT0, TU0, AT0 and AU0 of level 0.

As the distributor brush passes over the even-numbered segment 4 to 22 of the ring R1, relay P1 operates and transmits battery at armatures 88 and 89 and break contacts of relay AG, conductors 4 of cables 91 and 101, make contact and armatures 92 and 102 of relay P1, conductors 93 and 103, make contacts and armatures of relays IDENT, TIME and ALT to the windings of the indicators ITO and AU0 of level 0 and thence by way of their associated switch contacts and conductors 1 to 6 of cable 239 and make contacts of relay GA0 to ground, thereby causing the indicators ITO to AU0 of level 0 to be stepped ahead to their blank positions by impulses received from relay P1 during the passage of the brush DB1 over the even-numbered segments 4 to 24 of the ring R1. As each indicator moves into its blank position, the associated switch contact is opened, thereby removing ground from the indicator impulse circuit. A circuit is also closed from battery at contacts 357 of key W0, conductor 8 of cable 88, armature 358 and break contact of relay AG, conductor 3 of cable 88, make con-

tact and armature 359 of relay P1, conductor 361, contacts 362 of relay GA0, conductor 0 of cable 345, winding of fix indicator FSO associated with level 0 and switch contacts 363 thereof to ground at 364. When sufficient impulses have been transmitted by relay P1 during the passage of the brush over even-numbered segments 4 to 22 of the ring R1, the fix indicator FSO is restored to its blank setting concurrently with the indicators of level 0 and its switch contact 363 is moved out of engagement with its grounded contact 364 and into engagement with its contact 365.

When the brush engages segment 24 of the ring R1, ground is applied to conductor 13 extending to the winding of relay AG from whence the circuit is continued by way of conductor 114, break contact and armature 115 of relay SEQ to battery, thereby causing relay AG to operate and lock by way of its armature 116, conductor 1 of cable 47, break contact and armature 117 of relay REL to ground. The operation of relay AG at its armature 125 applies ground to conductor 126, contacts 127 of relay GA0 and thence to the winding of relay G0, causing relay G0 to operate. The operation of relay G0 at its contacts 366 applies ground to conductor 10 of cable 345, switch contacts 365 and 363 of the fix storage indicator FSO and winding thereof, conductor 0 of cable 345, contacts 362 of relay GA0, conductor 361 extending to pulsing contacts of the relays P1, P2, P4 and P7. The operation of relay AG at its armatures 88, 89 and 358 removes battery from the pulsing contacts of armatures 92, 102 and 359 of relay P1 and since, in the assumed example, no fix or data keys of the keyset are operated, the operation of relays P1, P2, P4 and P7 as the distributor brush passes over the group of segments 26 to 44 of the ring R1 is ineffective, and the indicators of level 0 in addition to the fix indicator FSO remain at their blank settings.

As brush DB1 comes in engagement with segment 45 of the ring R2, relay REL operates and at its armature 117 and make contact therof applies ground by way of conductor 258, armature 259 and break contact of relay SEQ, conductor 1 of cable 226, contact 261 of relay KS to the winding of the key release magnet KR, thereby causing the key release magnet to operate and release the key W0. As armature 117 of relay REL moves away from its break contact, ground is removed from conductor 1 of cable 47 thereby causing relay AG to release.

The release of key W0 removes ground from conductor 219 thereby releasing the seeker relay K which at its armature 220 removes battery from the winding of relay KS, causing relay KS to release. The release of relay KS at its contacts 231 removes ground from conductor 0 of cable 232 thereby releasing relay GA0. The release of relay AG at armature 125 thereof caused relay G0 to release. The release of relay KS at its contacts 225 removes ground from the winding of the start magnet SM2 thereby releasing the start magnet and causing the brushes of distributor DR2 to come to rest at the completion of their revolution. The indicators of level 0 of the flight progress board and the fix indicator FSO are now restored to their blank positions with the wipers of the identification indicators ITO and IU0 and the wiper of the fix indicator FSO in engagement with their blank terminals BL.

In the event that the keyset operator desires to post a new flight in the horizontal space or level when the indicators thereof and the associ-

ated fix indicators have been restored to their blank settings, the fix storage indicator may be set to the appropriate position concurrently with the actuation of the indicators of any of the ranges of the horizontal position; as for example, with the indicators associated with the flight identification number. If the operator desires to set up a flight number on the flight identification indicators of level 0, for example, associated with fix 3, the following keys of his keyset are operated: Fix 3, HORIZ. POS. key 0, DATA TENS and UNITS keys corresponding to the flight number to be posted and the range key IDENT. The operation of fix key 3 applies battery by way of conductor 8 of cable 88 and thence to armature 358 and break contacts thereof of relay AG, conductor 3 of cable 88, make contact and armature 359 of relay P1, conductor 361, contacts 362 of relay GA0, conductor 0 of cable 345, and thence to the winding of fix storage indicator FSO, the circuit continuing by way of switch contacts 363 and 365, conductor 10 of cable 345, contacts 366 of relay G0 (when operated) and thence to ground. The operation of relay P1 as the brush DB1 passes over the even-numbered segments 4 to 22 of the ring R1 is without effect for the reason that relay G0 does not operate and close its contacts 366 until segment 24 is engaged by the brush DB1.

The operation of fix key 3 applies battery to conductors 1 and 2 of cable 88 extending to the contacts associated with armatures 158 and 160 of relays P1 and P2 respectively. The operation of relays P1 and P2 as the brush crosses segments 26, 28 and 30 of the ring R1, applies three battery impulses to conductor 361, contacts 362 of relay GA0, conductor 0 of cable 345, winding of indicator FSO, switch contacts 363 and 365 of fix indicator FSO, conductor 10 of cable 345, contacts 366 of relay G0 and thence to ground. As the first impulse is received over the circuit just described, indicator FSO is advanced to its position 1, and switch contact 363 is moved out of engagement with contact 365 and into engagement with grounded contacts 364. The fix indicator FSO is thus stepped ahead on a circuit including grounded contact 364 to display the digit 3, the actuation of the fix indicator FSO occurring during the actuation of the flight identification indicators ITO and IUO to their new settings.

Shifting the posted information to a new level

When a flight has landed, as for example, the flight 15 posted at the 0 level of the flight progress board, the indicators of this flight are restored to their blank positions. The operation of the system to shift the information now posted on levels 1, 2 and 3 to levels 0, 1 and 2 respectively and restoring the indicators of level 3 to blank, will now be described.

The keys horizontal position 0 and change position 3 are operated and the range key SEQ is depressed.

The operation of key SEQ causes the seeker relay K to operate and arrest the seeker switch on one of its keyset positions. Relay KS now operates and locks by way of its contacts 224 to ground. The operation of key SEQ at its contact 263 applies ground to conductor 3 of cable 226 and conductor 264 thereby operating relays SEQ and SEQ-1. With relay KS operated, ground at contacts 264 of key SEQ is applied to conductors 4, 5 and 6 of cable 88 thereby operating the range relays IDENT, TIME and ALT. 75

Since the change position key 3 is of higher denominational value than the horizontal position key 0, ground at contacts 265 of change position key 3 is extended by way of contacts 266 of horizontal key 3, contacts 267 of horizontal position keys 4 to 9, conductor 268, contacts 269 of relay KS and thence by way of conductor 271 to the windings of the transfer relays TR, TR1, TR2 and TR3, causing these relays to operate.

10 The sequence switch stepping magnet STM is operated by self-interruptions on a circuit including the winding of relay SR and the switch wiper C until the wipers reach their terminals 12, at which time the wipers come to rest. The 15 operating circuit for the stepping magnet STM includes the grounded terminals of level C of the switch to which ground is applied by the unoperated contacts of all change position keys except the operated change position key 3, the 20 ground to certain of the grounded contacts of level 3 being applied at contacts 225 of relay KS. Thus, with change position key 3 operated, ground is applied to all of the contacts of level 3 with the exception of contact 12, thereby stopping the switch with its wipers on their terminals 25 12. The operation of relay SR causes relay CI to operate and lock to ground on conductor 2 of cable 226. With relay CI operated, the release of relay SR operates relay SD, thereby interrupting the circuit to wiper C of the sequence switch. With relay SD operated, ground is applied to the start magnet SM2 to set the distributor DR2 into operation. A circuit is closed from the 30 grounded contacts of horizontal position key 0, conductor 0 of cable 229, contacts 231 of relay KS, conductor 0 of cable 232, armature 233 and break contact of relay GC1, conductor 0 of cable 234, armature 235 and make contact of relay SEQ-1, conductor 0 of cable 272, and thence to the winding of relay G0, thereby causing relay G0 to operate.

The distributor DR2 now makes five revolutions during which the indicators of level 3 are restored to their blank positions and the information posted on the indicators of levels 1, 2 and 3 is shifted to levels 0, 1 and 2 respectively. The operation of the system occurring during the revolutions of the distributor DR2 are similar to the operations for changing the sequence of the information posted and the circuits are similar to those previously described. For this reason the circuit operation recurring during the first and each subsequent revolution of the distributor DR2 will be described only generally.

55 During the first revolution of the distributor, the sequence switch is stepped ahead from terminal 12 to terminal 14 and the information stored in the indicators of level 0 is transferred to the storage indicators S1. Since in the assumed example, the indicators of level 0 are at their blank positions with their associated switch contacts disengaged from one another, there is no transfer of digit information from the 0 level indicators to the storage indicators S1 during this first revolution, the storage indicators of S1 remaining on their blank settings.

During the second revolution of the distributor DR2, the sequence switch is stepped ahead to its position 16 and the information posted by the indicators of level 3 is transferred to the storage indicators S2. During the latter part of this revolution the storage indicators S1 are connected to the indicators of level 3 but since no digit information is stored in the indicators S1,

the indicators of level 3 remain on their blank settings.

During the third revolution of the distributor, the sequence switch is stepped ahead to its position 18 and the information posted on the indicators of level 2 is transferred to the storage indicators S1. During the latter part of the revolution of the distributor, the information stored in the storage indicators S2 during the second revolution of the distributor is transferred to the indicators of level 2.

The distributor now makes a fourth revolution and causes the sequence switch wipers to be stepped ahead to their terminals 20 and the information posted by the indicators of the level 1 is transferred to the storage indicators S2. During the latter part of this revolution the information stored during the third revolution is transferred from the storage indicators S1 to the indicators of level 1.

The distributor now makes a fifth revolution thereby stepping the wipers of the sequence switch ahead to their terminals 22 and connecting the indicators of level 0 to the group of storage indicators S1. There is no transfer of digit information from the indicators of level 0 to the storage indicators S1 at this time for the reason that the indicators of level 0, as will be recalled, have been restored to their blank settings during the first revolution of the distributor and their switch contacts, therefore, are in open position at this time. During the latter part of the fifth revolution of the distributor DR2, the flight information stored in the storage indicators S2 during the fourth revolution of the distributor is transferred to the indicators of level 0. The blank settings of the indicators of level 0 have been transferred to the indicators of level 3 and the settings of the indicators of levels 1, 2 and 3 have been shifted to levels 0, 1 and 2 respectively and the storage indicators S1 and S2 have been restored to their blank positions.

The engagement of segment 23 of the ring R1 by the brush DB1 caused the switch wipers to be moved into engagement with their terminals 22 at which time ground at the operated contacts of horizontal position key 0 was applied by way of conductor 0 of cable 229, contacts 231 of relay KS, conductor 0 of cable 232, armature 233 and make contact of relay GCI, conductor 0 of cable 348, make contact and armature 343 of relay TR1, contact 22 and wiper CP of the sequence switch, winding of relay EQ to battery thereby causing relay EQ to operate. As brush DB1 engages terminal 45 of the ring R1, relay REL operates and applies ground by way of its armature 117 and make contact, conductor 258, make contact and armature 349 of relay EQ, conductor 1 of cable 226, contacts 261 of relay KS to the winding of the key release magnet KM, thereby causing the key release magnet to operate and release the range key SEQ. The release of key SEQ releases relay K and the seeker switch. The release of relay KS, as battery is removed from its winding at armature 220 of relay K, removes ground from conductor 2 of cable 226 thereby releasing relays C1 and CG. Relay SD releases causing the start magnet SM2 to release and arrest the distributor brushes at the completion of their fifth revolution.

Reassigning the groups of indicators to different fix designations

Referring now to Fig. 9 of the drawings, there is shown thereon a flight progress board com-

prising groups of indicators associated with designation strips 367 bearing the markings FIX 1, FIX 2 and FIX 3 or marked in any other suitable manner as, for example: Camden, Baltimore and 5 Washington airport respectively. Each of these strips is provided with means whereby the number of horizontal rows of indicators or indicator levels assigned to each fix may be varied at will. Whereas three levels of indicators are assigned 10 to fix 1 and fix 2 respectively and four levels of indicators are assigned to fix 3, it will be understood that many more levels of indicators may be provided if desired and more than three fix designation strips may be employed; also, the 15 number of horizontal rows of indicators assigned to each designation strip may be increased or decreased in accordance with the requirements of service for which the system is adapted. The manner in which this is accomplished will be best 20 understood by consideration of a particular example. Assume, for example, that the indicators of level 3 have been restored to their blank settings and it is desired to include the indicators of this level within the group of indicators of fix 2 and exclude these indicators from the indicators of fix 3.

The fix designation strip or cardholder 367 is adjustably mounted on the flight progress board in such a manner that it may be moved upward 30 or downward and retained in its moved position by any suitable means; such as: pins, clips, hooks and the like, or by means of a cord and pulley arrangement. In the preferred embodiment of the invention shown on Fig. 9 the strips 367 are each provided with pins 368 adapted to engage any of the holes 369 on the face of the board. When it is desired to include the indicators of level 3 within the group of indicators assigned to fix 2, the cardholder designated FIX 3 is moved 35 to a position intermediate the indicators of levels 2 and 3 in which moved position it is securely held by the pins 368. The lowermost row of indicators assigned to fix 2 are now set to their blank positions and the indicators of fix 3 comprise the levels 2, 1 and 0.

As additional flight information is received by the local keyset operator, it is posted preferably on a group or level of indicators within the desired fix above the groups of indicators on which other flight information is posted.

With the designation strip FIX 3 in position intermediate the indicators of levels 2 and 3, the blank settings of the indicators of level 3 are transferred to the indicators of level 6 and the information posted on the indicators of levels 6, 5 and 4 are shifted to the indicators of levels 5, 4 and 3 respectively. This is accomplished by a single keyset operation as follows: Keys horizontal position 3 and change position 6 are operated and the range key SEQ is depressed. The operation of key SEQ causes relay K to operate and arrest the seeker in one of its keyset positions. Relay KS operates and locks by way of its contacts 224 to ground. Since the operated change position key is numerically greater than the operated horizontal position key, the operation of relay KS causes the transfer relays TR, TR1, TR2 and TR3 to operate. With relay KS operated ground is applied to all of the terminals of bank C of the seeker switch except the terminal 6 thereof, the terminal 6 being disconnected from ground at contacts 281 of the change position key 6 which are in open position with this key operated. The sequence switch therefore steps on self-interruptions until terminal 6

is engaged by the switch wipers, at which time the operating circuit for the stepping magnet STM is opened at terminal 6 of level C of the switch.

The operation of relay SR in response to the first flow of current through the stepping magnet STM causes relay C1 to operate and lock to ground on conductor 2 of cable 226. The release of relay SR applies battery by way of armature 293 and make contact of relay C1, armature 294 and break contact of relay SR, winding of relay SD, to ground on conductor 2 of cable 226 thereby operating relay SD. A circuit is now closed from grounded armature 291 and break contact of relay SR, make contact and armature 295 of relay SD, conductor 228, winding of the start magnet SM2 to battery thereby operating the start magnet and setting the distributor DR2 into operation. The distributor makes five revolutions in the example assumed, the sequence switch wipers stepping ahead to their terminals 3 during the first revolution of the distributor and coming to rest on their terminals 16 when the fifth revolution of the distributor has been completed. The manner in which the storage indicators S1 and S2 are employed to transfer the blank settings of the indicators of level 3 to the indicators of level 6 and shift the settings of the indicators of levels 6, 5 and 4 to the indicators of levels 5, 4 and 3 respectively will be apparent from the foregoing description and these circuits therefore will not be described in detail.

Changing settings of fix indicators

There is associated with each horizontal row or level of indicators a fix storage indicator, the setting of which is in accordance with the fix to which each level of posting indicators has been assigned. When the arrangement shown on Fig. 9 of the drawings is employed, the fix indicators FS0, FS1, FS2 and FS3 associated with the designation strip FIX 3 are each set on their positions 3 with their wipers in engagement with their terminals 3. The fix indicators FS4, FS5 and FS6 associated with the indicators of levels 4, 5 and 6 respectively included within the group designated FIX 2 have their wipers resting on terminals 2. In a similar manner the fix indicators FS7, FS8 and FS9 associated with the indicators of fix 1 have their wipers resting on their terminals 1. In the preceding example wherein the designation strip FIX 3 was moved to a position intermediate the levels 2 and 3 of the flight announcing board, it now becomes necessary to change the settings of the fix indicator FS3 from position 3 to position 2 in accordance with the number of the fix to which the indicator is now assigned. This is accomplished by operating the following keys of the key board: fix key 2, horizontal position key 3 and the range key FS. The operation of key FS applies ground to conductor 219 thereby operating relay K and arresting the seeker in one of its keyset positions. When this occurs relay KS operates and locks to ground at its contact 224. The operation of horizontal position key 3 applies ground by way of conductor 3 of cable 229, operated contacts of relay KS, conductor 3 of cable 232, armature 353 and break contact of relay GC1, conductor 3 of cable 236, armature 354 and break contact of relay SEQ-1, conductor 3 of cable 75, winding of relay GA3 and thence to battery, thereby causing relay GA3 to operate. Relay KS at its contacts 225 applies ground to conductor 2 of cable 226, break contact and armature 227

of relay SEQ, conductor 228 and thence to the winding of the start magnet SM2, causing the start magnet to operate and set the distributor into operation. As the brush DB1 passes over even-numbered segments 4 to 22 of the ring R1, relay P7 operates and transmits ten indicator restoration impulses over the following circuit: Battery, operated contacts 369 of the fix key 2, conductor 8 of cable 88, armature 358 and break contact of relay AG, conductor 3 of cable 88, make contact and armature 359 of relay P1, conductor 361, contacts 362 of relay GA3, conductor 3 of cable 345, winding of fix storage indicator FS3, switch contacts 371 to ground at 372. When sufficient impulses have been received to restore the fix indicator FS3 to its blank position, switch contact 371 is moved out of engagement with contact 372 and into engagement with contact 373.

As the brush DB1 engages segment 24 of the distributor DR2, relay AG operates and applies ground by way of its make contact and armature 125 to conductor 126, contacts 127 of relay GA3, and thence to the winding of relay G8, causing relay G8 to operate.

As the brush DB1 passes over segments 28 and 30 of the ring R2, relay P2 operates and transmits two impulses through the winding of fix storage indicator FS3 over the following circuit: Battery at contacts 373 of fix key 2, conductor 374, contacts 375 of relay KS, conductor 2 of cable 88, make contact and armature 169 of relay P2, conductor 361, contacts 362 of relay GA3, conductor 3 of cable 345, winding of fix indicator FS3, switch contacts 371 and 378 thereof, conductor 13 of cable 345, contacts 366 of relay G8, and thence to ground. As the distributor brush passes off segment 30 of the ring R1, relay P2 releases thereby stepping the wiper of the indicator FS3 into engagement with its terminal 2. As segment 45 of the ring R1 is engaged by the brush DB1, relay REL operates thereby applying ground to conductor 2 of cable 226 and causing the key release magnet to operate and restore the range key FS, thereby releasing the seeker relay K and the keyset relay KS. The release of relay CI as ground is removed from conductor 2 of cable 226 by the release of relay KS causes relay SD to release and removes ground from the winding of the start magnet SM2, thereby arresting the brush DB1 at the completion of its revolution.

The extreme flexibility of the system is further demonstrated by the arrangement of parts and circuits therefor such that if, for example, when posting the board by keyset operation to display the flight number and such other information as altitude or time, the appropriate fix key of the keyset had been actuated the selected fix indicator will receive actuating impulses during the time that the indicators of the selected level are receiving impulses.

The system also provides an indicator such as the lamp 180 shown on Fig. 5 of the drawings which operates whenever the relays DT or DU are set to positions representative of code signals received other than the code signals for the digits 1 to 9 and 0 such as may result from the improper operation of the teleprinter keyboards of Fig. 1 or from any other cause such, for example, as the failure of the line L or, in the case of radio signals received, from static conditions resulting from severe electrical storms and the like. When this indication of an improper signal is received an attendant at the airway traffic

control center is thus immediately apprised of this condition whereby he may issue instructions to the sending operator, by means of the communication facilities provided, that his message has been incorrectly received and request that the message be repeated.

Certain features of operation of the system herein disclosed, particularly with respect to transferring or shifting selectively the posted information from one of the groups of indicating devices of the series to another of the groups of the series, represent an improvement on a similar system disclosed and claimed in a copending application of William F. Quinby, Serial No. 304,736, filed November 16, 1939, for Posting system, assigned to the assignee of the instant case.

While the invention has been described in detail with respect to a certain preferred example thereof which gives satisfactory results, it will be understood by those skilled in the art after understanding the invention that various features of the system disclosed and claimed herein may advantageously be employed in communication and posting systems other than airway traffic control systems, and that various modifications and changes may be made without departing from the spirit and scope of the invention, and it is intended therefore, in the appended claims to cover all such changes and modifications.

What is claimed as new and desired to be secured by Letters Patent of the United States is:

1. A system for posting information regarding a plurality of items, comprising an announcing board having a plurality of groups of electro-responsive indicators assignable at different times to different ones of said items, each group of indicators including an indicator actuatable to different settings for posting the designation of the item and other indicators selectively actuatable to different settings for posting information in regard to said item, means for selectively setting any of said item designation posting indicators to designate a given item, a source of posting signals comprising item designation and item information in regard to said items, means responsive to said designation signals for automatically finding and selecting the particular group of indicators having an item designation setting corresponding to said item designation signals and means controlled by said item information signals for actuating said other indicators of the selected group for posting the information represented thereby.

2. A system for posting information regarding a plurality of items, comprising an announcing board having a plurality of groups of electro-responsive indicators assignable at different times to different ones of said items, each group of indicators including an indicator actuatable to different settings for posting the designation of the item and other indicators selectively actuatable to different settings for posting information in regard to said item, means for selectively setting any of said item designation posting indicators to designate a given item, a source of posting signals comprising item designation and item information in regard to said items, means responsive to said designation signals for comparing the settings of the various item designation indicators with the item designation signals, means controlled by said comparing means for selecting a particular group of indicators having an item designation indicator with a setting cor-

responding to the item designation signals, and means controlled by said item information signals for posting the information represented thereby on the selected group of indicators.

3. A system for posting information regarding a plurality of items, comprising an announcing board having a plurality of groups of electro-responsive indicators assignable at different times to different ones of said items, each group of indicators including an indicator actuatable to different settings for posting the designation of the item and other indicators selectively actuatable to different settings for posting information in regard to said item, said groups of indicators being disposed in serial order, means for selectively setting any of said item designation posting indicators to designate a given item, means for selectively transferring the settings of any one of said groups of indicators including the item designation indicator thereof to another of said groups of indicators to change the serial order in which the items of information are posted on the announcing board, a source of posting signals comprising item designation and item information in regard to said items, means responsive to said designation signals for automatically finding and selecting the particular group of indicators having an item designation setting corresponding to said item designation signals irrespective of the instant serial order in which the items of information are posted, and means controlled by said item information signals for actuating said other indicators of the selected group for posting the information represented thereby.

4. A system for posting information regarding the movements of aircraft, comprising an announcing board having a plurality of electro-responsive posting devices each assignable at different times to different flights respectively of said aircraft, each posting device including a plurality of means respectively actuatable to different settings for posting flight designation and flight information corresponding to the associated aircraft while in flight, means for setting any of said flight designation posting means to designate a given flight, a source of posting signals comprising flight designation and flight information in regard to said aircraft, means responsive to said designation signals for automatically finding and selecting the particular posting device having a flight designation setting corresponding to said flight designation signals, and means controlled by said flight information signals for posting the information represented thereby on the selected posting device.

5. A system for posting information regarding the movements of aircraft, comprising an announcing board having a plurality of electro-responsive posting devices each assignable at different times to different flights respectively of said aircraft, each posting device including a plurality of means respectively actuatable to different settings for posting flight designation and flight information corresponding to the associated aircraft while in flight, means for setting any of said flight designation posting means to a given designated flight, means in said aircraft in flight for transmitting posting signals comprising flight designation and flight information, means responsive to said designation signals for automatically finding and selecting the particular posting device having a flight designation setting corresponding to said flight designation signals, and means controlled by said

flight information signals for posting the information represented thereby on the selected posting device.

6. A system for posting information regarding the movements of aircraft, comprising an announcing board having a plurality of electro-responsive posting devices each assignable at different times to different flights respectively of said aircraft, said posting devices being arranged in groups classified in regard to markers traversed by the aircraft in flight, each posting device including a plurality of means respectively actuatable to different settings for posting flight designation and flight information corresponding to the associated aircraft, means for setting any of said flight designation posting means to designate a given flight, a source of posting signals comprising flight and marker designation and flight information in regard to each of said aircraft, means responsive to said flight and marker designation signals for automatically finding and selecting a particular marker group of posting devices and a posting device within said group having a flight designation setting corresponding to said flight designation signals, and means controlled by said flight information signals for posting the information represented thereby on the selected posting device.

7. A system for posting information regarding the movements of aircraft, comprising an announcing board having a plurality of electro-responsive posting devices each assignable at different times to different flights respectively of said aircraft, said posting devices being arranged in groups classified in regard to markers traversed by the aircraft in flight, each posting device including a plurality of means respectively actuatable to different settings for posting flight designation and flight information corresponding to the associated aircraft, means in said aircraft for transmitting while in flight posting signals comprising flight and marker designation and flight information, means for setting any of said flight designation posting means to designate a given flight, means responsive to said designation signals for automatically finding and selecting a particular marker group of posting devices and a posting device within said group having a flight designation setting corresponding to said flight designation signals, and means controlled by said flight information signals for posting the information represented thereby on the selected posting device.

8. In a traffic control system for aircraft and the like, receiving means comprising a flight progress announcing board having a plurality of electro-responsive posting devices disposed in adjacent relationship with one another for displaying concurrently in a predetermined order items of flight progress information respectively concerning a plurality of different aircraft while in flight, each of said devices being adapted to display said information in regard to one of said aircraft, means for transmitting to said receiving means electrical signals representative of said flight progress information in regard to any of said aircraft, said receiving means being responsive to said incoming signals for selecting one of said devices on which the information concerning a particular one of said aircraft is posted and for actuating the selected device to cause it to display the information received, means for transmitting transfer signals to said receiving means, means responsive to said trans-

fer signals and to means operable in accordance with the information set up on the posting devices for automatically transferring the information from certain of said posting devices to other of the devices, depending upon the particular transfer signals received, to change the sequential order in which the items of information in regard to the different aircraft are displayed on said devices, and means in said receiving means responsive to said incoming signals for causing the proper posting device to be selected when the sequential order of the items of information displayed on said devices has been changed.

9. In a traffic control system for aircraft and the like, receiving means comprising a flight progress announcing board having a plurality of groups of electro-responsive posting devices for displaying concurrently in a predetermined order in each of said groups items of flight progress information respectively concerning a plurality of different aircraft while in flight, one of said devices in each group being adapted to display information in regard to one of said aircraft, means for transmitting to said receiving means electrical signals representative of said flight progress information in regard to any of said aircraft, said receiving means being responsive to said signals for selecting the group of devices and the device within the group on which the information concerning a particular one of said aircraft is posted and for actuating the selected device to cause it to display the information received, means for transmitting transfer signals to said receiving means, means responsive to said transfer signals and to means operable in accordance with the information set up on the posting devices for automatically transferring the information from certain of said posting devices in one of said groups to other of the devices in said one of the groups, depending upon the particular transfer signals received, to change the sequential order in which the items of information in regard to the different aircraft are displayed on said one group of devices, and means in said receiving means responsive to said incoming signals for causing the proper posting device in said one group to be selected when the sequential order of the items of information displayed on said devices has been changed.

10. In a traffic control system for aircraft, a receiving station comprising a flight progress announcing board having a plurality of electro-responsive posting devices respectively for displaying concurrently flight progress information concerning a plurality of aircraft while in flight, means for assigning at will any of said posting devices to a corresponding flight, means for transmitting from a plurality of points in the flight information zones of said aircraft messages comprising telegraphic signals representative of flight identification and flight information in regard to the aircraft, a plurality of devices each for receiving and storing said transmitted messages in regard to a particular one of said aircraft, means including seeker mechanism common to and controlled by said storage devices for causing the stored messages to be retransmitted successively in predetermined order, means at said first named receiving station for receiving and storing said retransmitted messages, means for decoding the retransmitted signals comprising the stored messages and for automatically finding the posting devices assigned to the particular flights respectively to which the

messages relate, and means for causing the decoded signals to actuate said assigned posting devices to display thereon the flight information retransmitted.

11. In a traffic control system for aircraft, a receiving station comprising a flight progress announcing board having a plurality of electro-responsive posting devices respectively for displaying concurrently flight progress information concerning a plurality of aircraft while in flight, means for assigning at will any of said posting devices to a corresponding flight, means for transmitting from a plurality of points in the flight information zones of said aircraft messages comprising telegraphic signals representative of flight identification and flight information in regard to the aircraft, a plurality of devices each for receiving said transmitted messages in regard to a particular one of said aircraft and for storing the messages on control forms, means including seeker mechanism common to and controlled by said control forms for causing the storage messages to be retransmitted successively in predetermined order, means at said first named receiving station for receiving and storing said retransmitted messages, means for decoding the retransmitted signals comprising the stored messages and for automatically finding the posting devices assigned to the particular flights respectively to which the messages relate, and means for actuating said assigned posting devices to display thereon the flight information retransmitted.

12. In a traffic control system for aircraft, a receiving station comprising a flight progress announcing board having a plurality of electro-responsive posting devices respectively for displaying concurrently flight progress information concerning a plurality of aircraft while in flight, means for assigning at will any of said posting devices to a corresponding flight, means for transmitting from a plurality of points in the flight information zones of said aircraft messages comprising telegraphic signals representative of flight identification and flight information in regard to the aircraft, and including end-of-message signals, a plurality of devices each for receiving and storing said transmitted messages in regard to a particular one of said aircraft, means associated with said devices and responsive to said end-of-message signals, means including seeker mechanism common to and controlled by said storage devices and said means responsive to the end-of-message signals for causing the stored messages to be retransmitted successively in the order in which they are received by said storage devices, means at said first named receiving station for receiving and storing said retransmitted messages, means for decoding the retransmitted signals comprising the stored messages and for automatically finding the posting devices assigned to the particular flights respectively to which the messages relate, and means for actuating said assigned posting devices to display thereon the flight information retransmitted.

13. In a system for posting information relative to the movements of aircraft, a plurality of incoming circuits each having means for transmitting signals comprising a message representative of flight information to be posted and including an end-of-message signal, receiving apparatus having a plurality of means for storing the messages received over said incoming circuits, means including distributing means for retransmitting the messages stored in said storage

5 end-of-message signal, means controlled by the means, signal sensing means responsive to said signals retransmitted by said distributing means for posting the flight information received by said receiving apparatus, seeker means automatically settable to different settings and having means for operatively connecting said storage means successively with said distributing means in accordance with the settings of said seeker means and the order of arrival of the messages over said incoming circuits, and means including said signal sensing means for initiating operation of said seeker means to cause the same to operatively connect said distributing means with a particular storage means having stored therein a message including said end-of-message signal.

10 14. In a system for posting information relative to the movements of aircraft, a display board comprising a plurality of groups of devices disposed in adjacent relationship with one another in serial order for posting flight information, each of said groups being classified according to a marker designation, means including a keyset and associated circuits for selecting the devices 15 of any desired group for operation, a storage device, and means controlled by said keyset for automatically transferring the settings of the selected devices associated with one of the marker groups to said storage device and thereafter to the devices of another marker group.

20 15. In a system of the character disclosed, a display board comprising a plurality of groups of indicators, said groups being disposed in serial order for posting information relative to the movements of aircraft, each of said groups of indicators being assignable to different flights of the aircraft in accordance with changing conditions incident to the flights of said aircraft, a keyset having a plurality of keys for selecting 25 any desired group of indicators, means controlled by certain of said keys for selecting a first group of indicators for operation, means controlled by other of said keys for selecting a second group of indicators for operation, means automatically effective when said first and second groups of indicators have been selected for transferring the settings of said first group of indicators to the second group of indicators, and means controlled by the operated condition of said keys for automatically shifting the original settings of said 30 second group and the groups intermediate said first and second groups of indicators to adjacent groups of indicators including the indicators of said first group.

35 16. In a system for posting information relative to the movements of aircraft, means for transmitting from a plurality of points in the flight information zones of said aircraft permutation code signals representative of flight designation and flight information in regard to said aircraft, means including a tape perforator for receiving said signals, and perforating a tape in accordance therewith, means including a tape transmitter controlled by said perforated tape 40 for retransmitting said signals, means for receiving and storing said retransmitted signals, an announcing board comprising a plurality of groups of electromagnetic indicators adapted to be operated impulsively step-by-step, means for 45 assigning at will any of said groups of indicators to a corresponding flight, means controlled by the retransmitted flight designation signals stored in said receiving means for automatically finding and selecting the groups of indicators assigned to the particular flights respectively to

which said flight designation signals relate, and means under control of said storage means for transmitting impulses to the selected indicators for actuating the indicators impulsively step-by-step to new settings to display said flight information.

17. In a system for posting information relative to the movements of aircraft, means for transmitting from a plurality of points in the flight information zones of said aircraft permutation code signals representative of flight designation and flight information in regard to said aircraft, means including a tape perforator for receiving said signals and perforating a tape in accordance therewith, means including a tape transmitter controlled by said perforated tape for retransmitting said signals, a telegraph printer responsive to said retransmitted signal for printing the flight designation and flight information in regard to all of said aircraft, other means for receiving and storing said retransmitted signals, an announcing board comprising a plurality of groups of electromagnetic indicators adapted to be operated impulsively step-by-step, means for assigning at will any of said groups of indicators to a corresponding flight, means controlled by the retransmitted flight designation signals stored in said other receiving means for automatically finding and selecting the groups of indicators assigned to the particular flights respectively to which said flight designation signals relate, and means under control of said storage means for transmitting impulses to the selected indicators for actuating the indicators impulsively step-by-step to new settings to display said flight information.

18. In a communication system, a plurality of communication circuits, means associated with each of said circuits for transmitting messages including end-of-message signals, receiving means including a tape perforator individual to each of said circuits for perforating a tape in accordance with the signals received, a tape transmitter associated with each of said tape perforators, an auto-stop for controlling each of said tape transmitters, receiving means common to said tape transmitters for receiving the messages transmitted thereby, a seeker mechanism for successively connecting said tape transmitters with said receiving means, means associated with said seeker mechanism and responsive to said end-of-message signals for disconnecting any of said tape transmitters from said receiving means, and means for preventing said last named means for disconnecting a tape transmitter from the receiving means depending upon the operative condition of said auto-stop.

19. In a system for posting information in regard to the movements of aircraft, the combination of a flight announcing board comprising a plurality of groups of electro-responsive display devices disposed in serial order and classified according to fix designations, each group being associated with a flight identification number and settable in accordance with the information to be posted thereby, means including a keyset for changing at will the serial order of the information posted by said group of display devices, means for transmitting from a plurality of points in the flight information zone of said aircraft, signals representative of flight designation and flight information in regard to said aircraft including an end-of-message signal, receiving and storage means for said signals, a seeker mechanism, means effective when said

end-of-message signal has been received by said receiving means for causing said seeker mechanism to operatively connect said storage means with said flight announcing board, means controlled by said flight identification signals for finding and selecting a group of posting devices corresponding to the flight identification signals received regardless of the serial order in which these devices have been assigned by said keyset, and means effective when the group of devices has been selected for causing the flight information represented by said posting signals to be posted by said devices.

20. In a system of the character disclosed, a flight announcing board comprising a plurality of groups of devices for posting information relative to the control of airway traffic, each of said groups of devices being disposed in serial order in accordance with one of the characteristics posted by said devices, means including a keyset having a plurality of groups of keys corresponding respectively to each of said groups of devices for transferring the settings of one of said groups of devices to another of said groups of devices, comparing means controlled by the settings of said groups of keys for determining whether the settings of the selected groups of devices are to be transferred to another group of devices of higher or lower serial order, and means controlled jointly by said groups of keys and said comparing means for selecting the group of devices from which the settings are to be transferred.

21. In a system of the character disclosed, a flight announcing board comprising a plurality of groups of devices, each group being adapted to post information relative to the control of one of the flights of aircraft, each of said groups of devices being disposed in serial order in accordance with one of the characteristics posted by said devices, a keyset having keys corresponding respectively to each of said groups of devices, selection means controlled by a setting of the keys of said keyset for selecting at will any two of the plurality of groups of posting devices for operation in accordance with the setting of said keyset, and means controlled by said setting of the keyset and automatically operable after the first of said groups of posting devices has been selected for selecting the second group of posting devices for operation under control of said setting of the keyset.

22. In a system for posting information relative to the movements of aircraft, a flight announcing board comprising a plurality of associated electro-responsive posting devices each assignable to different flights of the aircraft in accordance with changing conditions incident to the flights of said aircraft and classified in regard to the order of arrival of said aircraft at predetermined points, each posting device including means for posting the time of arrival of the associated aircraft at each of said points, means for selecting an adjacent one of the devices for operation, and means controlled by said selecting means for effecting a transposition in the settings of the said adjacent ones of the devices without changing the arrival sequence of the information posted by the remaining devices.

23. In a system for posting information in regard to the movements of aircraft, a flight announcing board comprising a plurality of groups of posting devices, each of said groups being assignable to different flights of the aircraft in accordance with changing conditions incident to

the flights of said aircraft, each of said groups being disposed in serial order in accordance with one of the characteristics posted by said devices, a keyset having a plurality of groups of keys corresponding respectively to each of said groups of devices, sequence means, means controlled by said groups of keys for selecting any desired group of posting devices for operation, and means controlled by said sequence means for operatively connecting said groups of keys successively to said selecting means whereby groups of posting devices are selected in succession in accordance with the operated condition of said groups of keys.

24. In an aircraft traffic control system, means for posting information regarding the movements of aircraft on an announcing board comprising a plurality of electro-magnetic posting devices disposed in adjacent relationship with one another and actuatable to different settings for displaying concurrently in a predetermined order items of flight progress information respectively concerning a plurality of different aircraft while in flight, means for transmitting to said announcing board posting signals comprising flight designation and flight information in regard to said aircraft, means responsive to said posting signals for actuating said posting devices to different settings to display said items of flight progress information, means for selecting any one of the posting devices and actuating the device to eradicate the information posted thereon, and means controlled by the settings of certain of the remaining posting devices for shifting the information posted thereon to adjacent ones of said devices including the device from which the information has been eradicated.

25. In a system for posting information relative to the movements of aircraft, a flight progress announcing board comprising a plurality of groups of posting devices disposed adjacent to one another in serial order, said posting devices being associated with different flights of aircraft respectively, a keyset including a first group of keys for selecting any of said devices for operation, impulse means including distributor structure for actuating the selected device to post the information set up on said keyset, means including a second group of keys for selecting another of said devices for operation, means jointly controlled by the settings of said first and second groups of keys for causing said distributor to pass through a predetermined variable number of cycles of operation depending upon the settings of said groups of keys, and means controlled by said distributor for operatively connecting the selected devices to said impulse means in succession whereby the selected devices are successively actuated to post the desired information.

26. In a system for posting information regarding the movements of aircraft, an announcing board comprising a plurality of electro-responsive posting devices each identified with a particular aircraft, said posting devices being arranged in groups classified in regard to markers traversed by the aircraft in flight, each posting device including means for posting designation and flight information corresponding to the associated aircraft, marker storage devices associated with said marker groups of posting devices, a source of posting signals including flight designation, marker and flight information signals, means including said marker storage devices and means responsive to said marker and

designation signals for automatically selecting a particular marker group of posting devices and a posting device within said group for operation, means controlled by said flight information signals for posting the information represented thereby on the selected posting device, and means for varying the number of posting devices assigned to any of said marker groups, said last named means comprising a second source of signals for selecting and changing the setting of at least one of said marker storage devices to cause it to associate one or more of said posting devices with another marker group of devices.

27. In a system for posting information regarding the movements of aircraft, an announcing board comprising a plurality of electro-responsive posting devices each assignable to different flights of the aircraft in accordance with changing conditions incident to said flights of the said aircraft, said posting devices being arranged in groups classified in regard to markers traversed by the aircraft in flight, each posting device including means for posting designation and flight information corresponding to the associated aircraft, a source of posting signals including designation and flight information signals, means responsive to said designation information signals for automatically selecting a particular marker group of posting devices and a posting device within said group for operation, means controlled by said flight information signals for posting the information represented thereby on the selected posting device when the information signals received correspond to one of a predetermined group of characters for posting said information, and signal means for indicating when the information signals received do not correspond to one of said predetermined group of characters.

28. In a system for posting information relative to the control of movements of aircraft, a keyset having means for setting up the flight information to be posted, means for storing the flight information set up by said keyset, a flight announcing board comprising a plurality of electromagnetic indicating devices respectively settable to display indicia comprising the items of flight information set up by said keyset, the indicating devices being disposed in groups such that the items of information may be displayed thereby in adjacent relationship with one another in accordance with any desired serial order, transmitting mechanism for actuating any group of indicators under control of the flight information stored in said storage means, means controlled by said keyset for selecting the devices of adjacent groups, and means controlled by the settings of said devices and effective when the devices of said adjacent groups have been selected for automatically interchanging the settings of the electromagnetic devices of said adjacent groups.

29. In a communication system, a plurality of channels over which signals comprising messages each including an end-of-message signal are received, means individual to each of said channels for receiving, storing and retransmitting the messages, an outgoing circuit common to said retransmitting means, means including a seeker for operatively connecting said retransmitting means in succession to said outgoing circuit, sensing means for each channel responsive to said end-of-message signal received over the associated channel for causing the seeker

means to operatively connect the associated retransmitting means to said outgoing circuit, and means responsive to the stored end-of-message signal for causing the seeker means to operatively disconnect the retransmitting means from said outgoing circuit when the message has been retransmitted over said circuit.

30. In a communication system, a plurality of channels over which signals comprising messages each including an end-of-message signal are received, means individual to each of said channels for receiving, storing and retransmitting the messages, an outgoing circuit common to said retransmitting means, means including a seeker for operatively connecting said retrans-

mitting means, in succession to said outgoing circuit, sensing means for each channel responsive to the message signals and said end-of-message signals and effective when an end-of-message signal is received over the associated channel for causing the seeker means to operatively connect the associated retransmitting means to said outgoing circuit, and means responsive to the stored end-of-message signal for causing the seeker means to operatively disconnect the retransmitting means from said outgoing circuit when the message has been retransmitted over said circuit.
